MULTIDENOMINATIONAL STAMP PRINTING AND VALUE METERING MACHINE

William J. Pearson and Thomas I. Brown, Los Angeles, Calif., assignors, by direct and mesne assignments, to Postal Automatic Machines, Inc., a corporation of Delaware

Application October 12, 1931, Serial No. 568,378

7 Claims. (Cl. 235—101)

This invention relates, generally, to meter mail machines intended for use by persons, firms, or corporations having a large volume of outgoing mail and operating under Government meter mail permit, and is more particularly directed to that type of machine which includes a printing mechanism and an associated value metering device so designed as to enable the user to purchase from the Government and have set up in the meter by a post office official any desired amount of prepaid postage, and to then enable the user to print meter mail stamp indicia of different selected denominations on envelopes, cards, etc., from time to time as desired, with the meter functioning in accordance with the re-nomination of each printed impression until a resetting thereof becomes necessary, at which time the mechanism will automatically become locked against further stamp printing operation until the meter is reset at the time of purchase of additional postage.

It is an object of the present invention to provide a multi-denominational machine of the pre-selective type embodying in a removable unit a printing mechanism including a plurality of stamp indicia printing members of different denominations adapted to be singly and selectively brought to printing position at the will of the operator; a co-operating impression means whereby impressions may be taken from the selected printing member; a total register associated with the printing mechanism for registering the value of all of the stamps printed; a meter associated with the printing mechanism and comprising a descending or subtracting counter adapted to be pre-set by a post office official to indicate an amount of prepaid postage purchased from the Government, which meter is automatically operated to deduct from such amount the value of each stamp printed, and is designated to provide a conveyer means adapted to feed envelopes, cards, or the like, singly and in succession to the printing mechanism; a driving mechanism for driving the conveyer and the printing mechanism; and control devices for the driving mechanism normally so actuated by each envelope as it arrives at the printing point or station as to cause the conveyer and the printing mechanism to be intermittently actuated in alternate sequence, whereby each envelope will be stationary while receiving a printed impression and the printing mechanism will be operated once for each envelope presented at the printing station.

55 Other objects are to incorporate in the ma-

chine a novel conveyer mechanism adapted to withdraw envelopes one at a time from the bottom of a vertical stack thereof contained in a receiving hopper and functioning to grip each envelope and translate it until it arrives at the 5 printing station, at which time the conveyer momentarily stops to hold the envelope stationary while being printed upon, the conveyer then continuing its operation to release and eject the printed envelope and bring the succeeding 10 envelope to printing position; to provide a conveyer of the suction or vacuum type, comprising a flexible endless belt provided with relatively spaced suction or vacuum cups, or similar means, adapted to be placed in communication with a 15 source of suction as they successively arrive at a position to grip an envelope in the hopper, then to be maintained in such communication with the suction source while translating the envelopes and to subsequently pass from such communication with the suction source and into communication with the atmosphere so as to break this suction grip on the envelopes as they are ejected from the machine; to provide perforations in said conveyer belt with each perforation communicating with one of the suction cups, and to associate with the upper flight of said belt a stationary track, grooved longitudinally to function as a suction manifold, with the belt perforations aligned with and adapted successively to register 30 with said manifold groove, the track being longitudinally bowed upwardly to maintain a leak-proof contact of the belt with the surface of the manifold portion thereof which functions as a valve seat, while the traveling perforated belt 35 functions as a valve controlling the suction influence of the suction cups; to so proportion the suction manifold in relation to the printing position as to cause each suction cup to maintain its grip on the respective envelope while at the 40 printing station; to provide a table so associated with the hopper that envelopes may be stacked horizontally upon the table within said hopper with their open flaps hanging downwardly over the side of the table in shingled relation, the 45 hopper being open at the opposite side and so related to said table as to accommodate envelopes of various widths; to dispose the upper flight of the conveyer belt in a longitudinal slot in said table with the table so disposed as to 50 support the envelopes being translated by the conveyer; to provide a moistening device so disposed in relation to the table as to effect a moistening of the depending envelope flaps as the envelopes travel singly along the table; to 55

employ a moistening device of the atomizing type functioning to produce a fine spray of fog of mist-like character through which the envelope flaps will pass to properly moisten their gummed surfaces, such moistening device being entirely free from contact with such gummed surfaces, whereby clogging of the device by accumulations of gum scraped from the moistened envelope flaps is prevented; to provide a moistening device disposed beneath the table which, for this reason, protects the bodies of the envelopes from being moistened by the spray, the machine thus being also capable of handling pre-sealed envelopes while the moistener is in operation and without moistening such pre-sealed envelopes, the moistener in such instance being functionally idle insofar as it concerns the productive operation of the machine in this particular use; to provide a sealing device associated with the table and functioning to fold each moistened envelope flap upwardly against the body of the respective envelope; and to provide a means for conditioning the machine for use merely as an envelope sealing device, in which use the metering printer unit may or may not be associated with the machine, and to this end there is provided a means for disabling the envelope-operated clutch-control trip, so that the drive for said unit will remain inactive while the conveyer drive will function continuously instead of intermittently whereby an uninterrupted translation of the successive envelopes past the moistening device, the sealing device, and the printing point, and the prompt ejection of the sealed envelopes will be effected.

It is a further object of the present invention to incorporate in the removable unit a complete printing mechanism including a printing means and a cooperating impression platen, and to so design the machine that, when said unit is associated therewith, the platen defines the printing station and is disposed within a recess in the table with its impression surface substantially flush with the envelope supporting surface thereof, and the printing means is positioned above the platen and the table so that the envelopes will, by the conveyer, be fed between the platen and the printing means, the platen being so disposed with relation to the normal position of the envelope-operated clutch-control trip that each envelope will be brought to rest upon the platen to receive a printed impression.

Another object is to provide a multi-denominational printing means having a plurality of indicia printing members adapted to be singly and selectively brought to printing position by manually operative pre-selective means, and to associate therewith a means for locking the printer during the pre-selective manual setting of the printing members so that a printing operation may be effected only when one of said printing members is properly adjusted to printing position; and a further object is to provide a means associated with said locking means and serving to prevent operation of the envelope-operated clutch control trip during such pre-selective setting of the printing members so as to prevent throwing in of the power drive of the printing mechanism.

Another object is to provide a single driving means adapted to drive a suction means for the conveyer and an air compressing means for the atomizing moistener, and to drive the conveyer and the metering printer unit through suitable clutch mechanism.

A further object is to provide a novel means for inking the printing member disposed at the

printing position, and to provide a guard means for preventing a fraudulent taking of an impression from said printing member, and means for so operating said guard as to expose the printing member only during an inking thereof and during an authorized printing operation. 5

Another object of the present invention is to provide a denominational value registering means associated with actuating mechanism, and differentially movable denominating means controlling said actuating mechanism, and to provide selector means adapted to be selectively operated to predetermine the values to be registered. 10

Another object is to provide a value registering means having a plurality of register wheels 15 and associated actuating elements arranged in different denominational banks, and to provide associated differentially movable denominating means for controlling said actuating elements, and selector means pre-selectively operative to 20 pre-set the denominating means.

Another object is to provide in the registering means register wheels of the ratchet type, whereby the associated actuating means will operate through a differential value denominating stroke 25 without operating said wheels and will then operate through a denominated return stroke to positively drive the register wheels.

Although various kinds of "meter mail" machines have heretofore been designed for the purpose of printing and metering postage values, none, insofar as we are aware, have contained mechanism capable of handling fractional postage values, such as $\frac{1}{2}$ cent, $1\frac{1}{2}$ cent, etc.; and, since it is believed that a machine of such character will constitute a valuable contribution to this art and will have exceptional utility in connection with Government postal systems, it becomes an important object of the present invention to provide a mechanism capable of printing 40 and metering fractional postage values. 30

Further, in the previously proposed machines of which we are aware, the meters are so arranged as to lock against further operation only when said meters register zero, thus, in many instances, locking the mechanism before the last operation is completed or compelling the user to have the meter reset while still containing unused prepaid postage, or to lock when operated a predetermined number of times. 50

Distinguishing from such machines, it is a further important object of the present invention to provide a descending meter which may be preset to indicate an amount of prepaid postage, and which may be operated to subtract postage 55 values from such amount until the total amount of prepaid postage has been exhausted and the meter wheels register zero, the meter being so designed as to permit a final operation in which the meter wheels are turned back past zero to 60 show a complementary figure by which an overdraft may be calculated; to provide an overdraft meter in which the final overdraft operation may be initiated when the meter wheels have been restored to zero or when they indicate an amount 65 of unused postage which is less than the denomination of the stamp to be printed during said final overdraft operation, whereby the actual overdraft may equal the value of the last stamp printed or may equal the difference between such 70 value and the amount of unused postage; and to provide a meter actuating means and an associated locking means for the means controlled by the meter.

Broadly, this meter has associated with it a 75

locking mechanism which functions at the end of the overdraft operation in which the meter wheels are moved back past zero to show various figures depending entirely upon the amount of unused postage remaining in the meter just prior to the overdraft operation and upon the denomination of the stamp printed during such overdraft operation, to lock the meter actuating mechanism against further operation; therefore, it is a further object of the invention to provide an overdraft meter and a locking mechanism associated therewith and so controlled thereby as to function at the end of the overdraft operation, regardless of the final figure indicated by the meter and regardless of the number of preceding operations of the meter.

Another object is to provide a descending postage meter capable of being set to register a given amount of postage and adapted to be operated to subtract different denominational values until the amount is exhausted and to be further operated varying degrees beyond zero to denote an overdraft.

Various other objects and advantages will be apparent from the following description of the accompanying drawings, which form a part of this disclosure and which illustrate a preferred form of embodiment of the invention.

Of the drawings:

Fig. 1 is a perspective view of a complete machine embodying the several features of the present invention.

Fig. 2 is a plan view, certain portions being broken away and in section to more clearly show the operating mechanisms.

Fig. 3 is a front elevation taken on the line 3—3 of Fig. 2.

Fig. 4 is an enlarged transverse vertical section taken on the line 4—4 of Fig. 2.

Fig. 5 is an enlarged detail vertical section taken on the line 5—5 of Fig. 2.

Fig. 6 is a detail view showing the conveyor belt with its two supporting pulleys and the vacuum manifold and track which supports the top flight of the belt.

Fig. 7 is a perspective view of the delivery end of the conveyor, the letter supporting table and the conveyor belt being broken away to more clearly show the construction of the vacuum manifold and track.

Fig. 8 is an enlarged transverse vertical section taken on the line 8—8 of Fig. 2.

Fig. 9 is an enlarged detail vertical section taken on the line 9—9 of Fig. 2.

Fig. 10 is a detail section taken on the line 10—10 of Fig. 8.

Fig. 11 is a detail section taken on the line 11—11 of Fig. 8.

Fig. 12 is an enlarged plan section taken on the line 12—12 of Fig. 3, showing the interior mechanism of the metering printer unit.

Fig. 13 is a vertical section taken on the line 13—13 of Fig. 12.

Fig. 14 is a vertical section taken on the line 14—14 of Fig. 12.

Fig. 15 is a vertical cross-section taken on the line 15—15 of Fig. 13.

Fig. 16 is a vertical cross-section taken on the line 16—16 of Fig. 13.

Fig. 17 is an enlarged plan view, partly in section, of the descending register or meter, taken on the line 17—17 of Fig. 13.

Figs. 18, 19, and 20 are transverse sectional views taken on the correspondingly numbered lines of Fig. 17.

Fig. 21 is a fragmentary sectional view taken on the line 21—21 of Fig. 20.

Fig. 22 is a fragmentary detail section taken on the line 22—22 of Fig. 12, showing respectively in full and in dotted lines, two positions of the cents wheel actuating elements as actuated in the registering of a five cents value.

Fig. 23 is a plan view of an envelope which has impressed thereon the indicia received in its passage through the machine.

Fig. 24 is a fragmentary detail section taken on the line 24—24 of Fig. 12, showing the means for actuating the printer guard.

Fig. 25 is a semi-diagrammatic perspective view of the value selector discs shown in Figs. 12 and 15.

The machine illustrated in the drawings is designed to provide a receiving hopper H disposed near one end of a table T^a and adapted to contain a stack H^s of envelopes horizontally disposed on the table with their open flaps hanging downwardly over the inner side of said table in shingled relation (see Fig. 4), so that the envelopes may be withdrawn singly and in succession from the bottom of the stack by a conveyor C and conveyed along the table past a flap-moistening device M and a flap-sealing device S and fed to a metering and printing unit M^p, where each envelope engages and operates a control trip T^r by means of which the driving mechanism D, contained in a rear housing R^h, is so controlled that, when an envelope operates said trip, the conveyor drive is thrown out, and the drive to the unit M^p is thrown in to operate the unit through a single printing and registering cycle to print a "metered mail" stamp on the envelope and operate the meter in accordance with the monetary value of such stamp, after which the drive to the unit is automatically thrown out and the drive to the conveyor is again established so that the conveyor will eject the stamped envelope from the machine and continue the feed of the succeeding envelope along the table to the printing position.

The supporting framework of the machine, as shown in Figs. 1 to 4 and 8, includes a base-plate 50 mounted upon suitable legs 51. Along the front portion of this base-plate there is provided a conveyor housing C^h having a front wall 52, an inner rear wall 53, and an end wall 54, the table T^a forming the top wall of said housing. The housing R^h, containing the driving mechanism D, consists of an outer end wall 100, an inner end wall 101, a rear wall 102, a top wall 103, and an inner front wall 104 which is slightly spaced from the inner rear wall 53 of the conveyor housing to provide a channel 55 (see Figs. 2 and 5) through which the flaps of the envelopes pass as they are fed along the table. This wall 104 is offset, as shown at 104^a in Fig. 2, and has a portion 104^c, adjacent the hopper H, which is spaced a considerable distance from the wall 53 to provide sufficient space adjacent the table at this point to accommodate the shingled flaps of all of the envelopes in the stack H^s, as shown in Fig. 4. Directly adjacent the inner end wall 101 of the housing R^h and directly behind the table, the base-plate has a raised shelf portion 59^a upon which rests the removable metering and printing head or unit M^p when the unit is associated with the machine proper.

Receiving hopper

The hopper H, which receives the stack H^s of envelopes to be sealed and stamped, is formed by a plate having a side wall 56 secured to the

portion 104^c of the inner wall of the housing R^h and extended outwardly a sufficient distance to accommodate long envelopes (see Fig. 2), and an end wall 57 extending across and above the table T^a. As shown in Figs. 1 and 4, the lower edge 57^a of the end wall 57 is spaced from the top surface of the table to permit feeding of the envelopes from the bottom of the stack, while the wall 56 extends downwardly past the open flap of the lowermost envelope.

In this hopper, the envelopes are horizontally stacked upon the table T^a with their open flaps extending downwardly in shingled relation over the inner edge of the table and against the inner wall 53 of the conveyer housing, as shown in Fig. 4; and, to maintain the envelopes properly disposed in this stacked relation, there is provided an aligning means comprising a pressure plate 58, which is hingedly supported in notches formed in studs 58^a carried by the walls 53 and 104^c, this pressure plate being urged to contact the envelope flaps by a vertically disposed leaf-spring 58^c carried by the wall 56 of the hopper. To prevent displacement of the pressure plate, it is provided with headed guide pins 58^e which are secured to the upper portion of the plate and slidably extend through apertures in the hopper wall 56 and the wall 104^c of the housing R^h, with their heads disposed within the housing R^h and serving to limit the tilting movement of the pressure plate.

As will be later described in detail, the conveyer provides a positive feed of each envelope as it reaches the bottom of the stack; to insure the desired one-by-one feed of the envelopes, there is provided a yielding baffle means adjacent the discharge end of the hopper. This baffle means is associated with the wall 51 of the hopper and includes duplicate devices B disposed at opposite sides of the conveyer C, each of the devices comprising a guide channel 59 secured to the hopper wall 57 and having a depending finger 59^a, the lower end of which is spaced from the table surface a distance equal to the thickest envelope which the machine is designed to handle. Slidable in each guide channel 59 is a vertical carriage 59^c, channel-shaped in cross-section, with its side walls nested within the side walls of the guide channel 59 and providing depending ears 59^e carrying a rubber-faced separator 59^r which, while preferably of roller form, is not freely rotatable since its shaft ends are, in assembling, riveted over sufficiently to cause a frictional bind between the roller and its supporting ears 59^e such as will prevent rotation of the roller during the operation of the machine but will permit a manual turning thereof to bring a fresh unworn portion of its periphery into operating position.

The carriage 59^c is connected to its guide channel 59 by pin and slot connections 59^s, the slots of which are slightly angled upwardly and forwardly, as shown in Figs. 1 and 3, and a spring 59^x connected to the guide channel 59 and to the carriage 59^c urges the separator roller 59^r toward the table. However, this spring could be eliminated if it is desired to depend entirely upon the weight of the carriage and gravity to perform this function.

In the operation of the machine, the fingers 59^a hold back the stack of envelopes while the lowermost envelope is being withdrawn by the conveyer; and, in case this envelope tends to withdraw other envelopes with it, due to friction between adjacent envelopes, such other en-

velopes will be held back by the separator rollers 59^r, thereby preventing a feed of more than one envelope at a time. It will be evident that the yielding nature of the separator carriages 59^c will provide compensation for envelopes of varying thicknesses and that each device B constitutes a yielding separator baffle which functions as a wiper to retain all but the lowermost envelope of the stack H^s within the receiving hopper.

10

Conveyer

Referring particularly to Figs. 1 and 2, it will be observed that the table T^a is provided with a longitudinal slot 60 which extends from a point 15 60^a within the hopper H, forwardly in the direction of feed, to the discharge end of the machine, and with particular reference to Figs. 2 and 4 to 8, it will be noted that, at each side of the table slot 60, the metal of which the table is 20 formed is bent downwardly to provide vertical depending flanges 60^c. Disposed within the table slot and between these two depending flanges is a stationary track member 61 which is supported at opposite ends upon cross-bars 62 and at its 25 medial portion upon a cross-bar 63, these cross-bars being secured to the walls 52 and 53 of the conveyer housing. At its opposite sides, the track member 61 is provided with longitudinal upstanding flanges 61^a defining a belt channel 61^c along 30 which the upper flight of the conveyer belt 64 travels, and the bottom wall of this channel is provided with two longitudinal grooves 61^e for the purpose of lessening the friction between the conveyer belt and the track, these grooves defining a 35 medial longitudinal rib 61^r which has milled in its upper surface a longitudinal groove 61^s having closed ends and extending approximately the full length of the track member. At each end the medial rib 61^r terminates in a projecting tongue 61^u; 40 and, at the cross-bar 63, there is a port 61^x communicating with the groove 61^s and with a conduit 65 leading to the suction side of a pump P^u, which is located within the housing R^h and which will later be described.

45

The conveyer belt 64 travels within the channel 61^c of the track member 61 and, at the hopper or receiving end of the table, is rove around an idler pulley 66, while at the discharge end of the table it is rove around a driven pulley 67, these 50 pulleys 66 and 67 being of similar form, each having side flanges 68 to maintain the belt against displacement and a medial groove 69 to accommodate the respective terminal tongue 61^u of the track member 61, the ends of the track member 55 being cut back as shown in Fig. 7 to afford proper clearance for the pulleys.

Attached to the outer surface of the conveyer belt 64 are four substantially rectangular suction or vacuum cups 64^a formed of pliable rubber or other suitable material. These cups 64^a are uniformly spaced around the conveyer belt and each is provided with a port 64^e which extends through the belt 64 in vertical alignment with the suction or vacuum groove 61^s in the 60 medial rib 61^r of the stationary track member 61.

With this arrangement, it will be quite evident that the medial grooved rib 61^r of the track member constitutes a suction or vacuum manifold over which the upper flight of the conveyer belt 70 travels and that the belt closely contacts said rib to close such manifold throughout the length of the groove 61^s. As shown in Figs. 3 and 6, it will be observed that the table T^a and the track member 61 are longitudinally bowed up- 75

wardly so that close contact of the upper flight of the belt with the upper surface of the medial rib or manifold 61^r will be assured, and by an examination of Fig. 6 it will be understood that, as each of the cups 64^a arrives at the feed end of the conveyer directly beneath the hopper H to contact the lowermost envelope therein, the port 64^c thereof will register with the manifold groove 61^s, thus connecting such cup with the source of suction. This will cause the cup to grip the lowermost envelope, and the continued travel of the conveyer will withdraw this envelope from the hopper and transport it along the table. As this cup passes the discharge end of the track member, its port 64^c will pass out of registry with the suction groove of the medial rib or manifold 61^r and be in free communication with the atmosphere, whereupon the suction grip of the cup upon the envelope will be broken, thus permitting the conveyer to discharge the envelope.

The idler conveyer pulley 66 is mounted on a shaft 70 which is journaled in bearings 71 secured to the respective outer and inner walls 52 and 53 of the conveyer housing, while the driven conveyer pulley 67 is mounted on a shaft 72 journaled in similar bearings 73, and, as shown in Figs. 2, 3, and 8, the shaft 72 is driven by belt 74 which is rove around a sheave 75 fixed to said shaft 72 and around a similar sheave 76 fixed on a conveyer drive shaft 77, this drive shaft 77 being journaled in a bearing 78 carried by the outer wall 52 of the conveyer housing and in a standard 79 which is located within the rear housing R^h, as shown in Fig. 8.

There is thus provided a conveyer which positively grips the lowermost envelope in the receiving hopper and conveys it along the table to the discharge end of the machine where it is released and ejected, with the upper surface of the medial rib or manifold 61^r serving as a stationary valve seat and the belt 64 with the ports 64^c communicating with the suction cups 64^a serving as a traveling valve means controlling the gripping function of the cups by connecting and disconnecting the cups at the proper times with the suction source.

Envelope flap moistener

The moistening device M is located within the conveyer housing M in position to moisten the gummed flap of each envelope as it is withdrawn from the receiving hopper H and is of the atomizing type designed to direct a spray of water of mist or fog-like fineness against the gummed surfaces of the envelope flaps as the envelopes pass from the hopper to the sealing device.

Referring to Figs. 4 and 5, and to the previous description of the receiving hopper, it will be understood that, as the lowermost envelope is withdrawn from the hopper, its depending flap will pass through the flap receiving channel 55, as indicated at 80 in Fig. 5, its gummed surface thus facing the inner wall 53 of the conveyer housing, and with particular reference to Fig. 3, it will be noted that this wall 53 is provided with a rectangular opening 81 through which the spray from the moistener is directed against the gummed flaps as the envelopes are carried along by the conveyer.

The spraying device which we preferably employ comprises an atomizing head 82 having a compressed air supply tube 83 communicating with an air supply conduit 84 leading to the pressure side of the pump P^u, and a suction tube 85, the lower portion 86^a of which is submerged

in water contained in a reservoir 86 secured in the base plate 50 and supporting the spraying device. This reservoir is supplied with water through a conduit 87 leading to a gravity water supply of the constant level type, and, as shown in Fig. 4, this conduit 87 communicates with a vented cup member 88 which is supported in a bracket 89 secured to the base plate 50, and which is provided with a valve unseating spike 90 projecting upwardly from its central portion, and a rubber ring 91 resting on its upper peripheral edge. An inverted bottle 92 contains a ball valve 92^a, and, when in position of use, the bottle rests upon the rubber ring 91 with its neck 92^c disposed within the cup member 88 and the spike 90 projected into the bottle to unseat the ball valve 92^a. Water from the inverted bottle maintains a constant water level in the cup member 88 and in the reservoir 86 of the spraying device, this level being approximately at the end of the inverted bottle neck. The purpose of the ball valve 92^a is to close the neck opening of the bottle, particularly when it is being inverted and positioned on the machine. To catch the drip or surplus water sprayed through the opening 81, there is provided a drip pan 93 secured to the wall 53 adjacent the bottom of the opening and having angled side walls extending upwardly on opposite sides of the opening, the bottom of the flap channel 55 being closed by a filler plate 94 and the pan 93 being provided with a drain 95 communicating with the conduit 87, as shown in Fig. 5.

In the operation of the machine, this moistening device directs a fine spray through the opening 81 and against the gummed surfaces of the envelope flaps passing through the flap channel 55, the surplus dropping into the pan 93 and draining into the gravity water supply. A particular advantage of this atomizing type of moistener is that no part of it contacts the gummed surfaces of the envelope flaps; and, for this reason, it is absolutely proof against becoming clogged with the gum as do those devices which moisten such flaps by direct contact.

Sealing device

The sealing device S serves to fold the moistened flap upwardly against the body of the envelope and, as shown in Figs. 2, 5, and 8, embodies an angled slot 96 cut in the inner portion of the table T^a, the forward edge 96^a of said slot being rolled downwardly, as shown in section in Fig. 8. At the inner forward end of this slot, the flap channel 55 is blocked by a filler 96^c (see Figs. 2 and 5) so that, as the envelope flap arrives at the slot 96, the flap is directed into the slot and, by engagement with the roller edge 96^a thereof, will, as the envelope is conveyed forwardly by the conveyer, be folded upwardly against the envelope body, thus sealing the envelope.

Envelope-operated control trip

As the envelopes are sealed, they are conveyed toward the printing point so as to be positioned upon the platen P^l of the metering and printing unit M^p, the printing portion of this unit overhanging the table and the platen, as shown in Figs. 1 to 8, so as to print the desired indicia upon each envelope as it is momentarily arrested to receive the impression. As shown in Fig. 2, the inner edge of the table T^a is provided with a notch 60^r of sufficient size to receive the platen P^l; and, when the unit M^p is in its

proper operating position with its platen thus positioned in said notch, the upper surface of the platen will be substantially flush with the upper surface of the table T^a or only slightly above such table surface.

In the forward portion of the notch 60^a , between the platen P^1 and the conveyer C , is positioned the upper end of the envelope-operated trip lever T^r . This trip lever is formed of two parts and comprises a main lever 97 and a terminal finger 97^a pivoted thereon and having an ear 97^c engaging the forward edge of the main lever to prevent forward rocking of the finger relative to the main lever, a spring 97^e attached to the ear and to the main lever 97 serving to urge the terminal finger 97^a to the extended position shown in Fig. 3. The main lever 97 is pivoted on a bracket 97^s secured to the base 50 and has a heel 97^v adapted to limit its return movement by engagement with the base. A link 98 connects the main lever 97 with a short arm 98^a secured to a clutch control rock-shaft 99 which extends into the rear housing R^h through a bearing 99^a carried by the wall 104 thereof, and a normalizing spring 97^x is attached to the lever 97 and to the machine base 50 .

The purpose of this jointed form of trip lever is to enable the operator, by manual means to be later described, to swing the terminal finger 97^a rearwardly until its free end is below the table surface and out of the path of the envelopes, and thus condition the machine for a certain specific use. However, since in the operation of the complete machine, the two-part trip lever operates in the same manner as would a one-piece lever, it will, in the following description, be referred to in that sense as the trip lever T^r , except in connection with the specific description of the manual means which rocks the terminal finger 97^a out of the envelope path.

From an examination of Fig. 3 of the drawings, it will be understood that, as an envelope approaches the printing station, its forward or lead edge will engage the trip lever T^r and rock it forwardly and downwardly to the position shown in dotted lines in that figure, the end of the lever wiping over the lead edge and along the under surface of the envelope which will hold the lever in this tripped position. At this time, the conveyer will have advanced the envelope to the proper position to receive the printed impression, and the rocking of the rockshaft 99 by this tripping of the trip lever T^r will have so controlled the clutch mechanism that the conveyer drive is thrown out and the drive to the metering and printer head M^p is thrown in. The envelope is thus momentarily arrested at the printing position while the printing mechanism operates through a single cycle to print the stamp indicia thereon.

The particular clutch arrangement for accomplishing this, and which will be described in detail in connection with the description of the driving mechanism, is so constructed as to automatically throw in the conveyer drive at the completion of each single printing cycle of the printing mechanism, whereby the envelope, after receiving the printed impression, is conveyed from the printing position to the end of the table, where it is released and ejected from the machine. With the passing of each envelope from the printing position, it wipes over the depressed trip lever, and when the lever is passed by the rear or trailing edge thereof, it is restored by spring 97^x to normal

position ready to be again actuated by the succeeding envelope.

Thus, it will be understood that the machine provides an intermittently driven vacuum conveyer for translating envelopes singly and in succession from a receiving hopper past flap-moistening and sealing devices to a printing position where each envelope is momentarily arrested to receive a printed impression and is then ejected from the machine.

5
10

Driving mechanism

The driving mechanism, which is enclosed within the rear housing R^h and is supported upon the base 50 , preferably includes an electric motor 105 having on its armature shaft a drive pulley 106 which is in direct driving connection, through a belt 107 , with a pulley 108 fixed on a jack-shaft 109 . This jack-shaft is journaled in bearings in the upper ends of opposite standards 110 secured to the base 50 , and between these standards and directly below the jack-shaft is the pump P^u .

Referring particularly to Fig. 9, it will be seen that this pump is of the reciprocatory type, having a cylinder 111 in which a piston 112 is reciprocated by means of a connecting rod 113 and an eccentric 114 on a drive shaft 115 . Outside the body of this pump, its drive shaft 115 has fixed thereto a sheave 116 connected by a belt 117 with a similar sheave 118 fixed on the jack-shaft 109 , thus providing a direct driving connection by means of which the pump is driven constantly at a uniform speed. The head 119 of the pump has an intake port 120 provided with a valve cage 121 containing an intake valve 122 which is of the spring-check type and is arranged to open only during the down or suction stroke of the piston 112 . The pump head 119 also has a discharge port 123 provided with a valve cage 124 containing a discharge valve 125 similar in kind to the intake valve 122 but arranged to open only during the up or compression stroke of the piston 112 . The discharge valve cage 124 communicates directly with the compressed air line 84 leading to the atomizer of the previously described moistening device M , and the intake valve cage 121 is provided with a T-head, one branch of which communicates directly with the suction conduit 65 leading to the suction or vacuum manifold 64^r of the previously described conveyer track member 64 , and the other branch of which provides a free air inlet 126 open to the atmosphere within the housing R^h and provided with a regulating valve 127 , a cover screen over the inlet 126 serving to exclude foreign matter from the pump system.

With the motor running, the pump is operated at a relatively high speed to produce a substantially constant and uniform supply of compressed air to operate the atomizer of the moistening device M and to create in the manifold of the conveyer C a substantially constant and uniform suction sufficient to cause the suction cups thereof to grip and translate the envelopes, the degree of this suction being properly regulated by the valve 127 to allow more or less free air to be drawn into the pump through the inlet 126 .

It will, of course, be obvious that various other types of pump could be substituted for the particular single cylinder reciprocatory pump herein disclosed and that, if desired, a separate air compressor could be provided for the moistening device, and a separate suction pump could be provided for the conveyer, changes of this nature

75

being considered as being well within the broader aspect of the present invention.

As shown in Figs. 2 and 8, a belt 139 transmits rotary motion from a pulley 131, fixed on the 5 jack-shaft 109, to a pulley 132 which is loosely journaled on an intermittently driven counter-shaft 133. The counter-shaft 133 is journaled in bearings in the upper ends of the standard 79 and of an opposite standard 134, and keyed there- 10 to is a bevel gear 135 meshing with a companion bevel gear 136 which is keyed to a main drive shaft 137. This drive shaft is journaled in radial thrust bearings 138 carried in the upper forked ends of the standard 134 and secured on its free 15 end is one member 139 of an "Oldham" coupling, the companion member 140 thereof being secured to the cam shaft of the removable metering and printing unit or head MP to be later described in detail.

20 For the present, it is sufficient to understand that this coupling provides a detachable connection between the drive shaft 137 and the cam shaft of the head MP, permitting an easy removal of the head from the machine and insuring a 25 proper re-establishment of this driving connection whenever head MP is disposed in its proper position upon the base of the machine.

To take up for wear and to insure a proper 30 intermeshing of the bevel gears 135 and 136, the counter-shaft 133 may be axially adjusted by means of a take-up screw 141 screw-threaded into the standard 79 and engaging a bearing ball 142 seated within a recess in the end of the shaft (see Fig. 8).

35 The inner end of the hub of the bevel gear 135 is provided with a radial flange 135a to which is riveted a counter-shaft drive disc 143, and loosely journaled on the shaft 133, adjacent the standard 79, is a conveyer drive sheave 144 which is connected by a belt 145 with a sheave 146 secured to the conveyer drive shaft 77.

40 In the preferred embodiment, the previously 45 mentioned control of the driving mechanism contemplates the employment of a conveyer clutch device C^e between the conveyer drive sheave 144 and the constantly rotating power pulley 132, and a drive clutch D^e between said pulley and the bevel gear 135 which drives the main drive shaft 137 of the machine.

50 Clutch devices

The clutch devices are illustrated in detail in Figs. 8 to 11; and, with particular reference to Fig. 8, it will be seen that the drive clutch D^e includes a clutch member 150 and that the conveyer clutch C^e includes a similar clutch member 150, these clutch members being secured on opposite sides of the power pulley 132 by rivets 132a. Referring to Figs. 10 and 11, it will be noted that each of these clutch members has the form of a toothed ratchet wheel with the radial sides of their several teeth facing in the direction of rotation, which is indicated by the arrows in said figures.

60 The drive clutch D^e, which is shown in elevation in Fig. 11, comprises the ratchet toothed clutch member 150 which is carried by the power pulley 132, and a clutch pawl 151 which is pivoted at 152 on the inner side of the counter-shaft drive disc 143, the pawl having a clutch tooth 151a aligned with the toothed clutch member 150 and a heel 151c projecting beyond the periphery of the drive disc 143, and provided with a spring 153 connected to its free end and to a pin 154 on said disc. The disc 143 has a radially

projecting stop abutment 155 disposed so that its forward face will align with the forward face of the heel 151c of the pawl 151 when the pawl is in the normal unclutching position shown in Fig. 11. A stop arm 156 is secured to a rock- 5 shaft 157 which is journaled in a bearing 134a, formed on the standard 134, and in a bearing 79a, formed on the standard 79, and normally engages the stop abutment 155 to lock the drive disc 143 against driving rotation, and also en- 10 gages the heel 151c to maintain the clutch pawl 151 in unclutching position against the tension of the spring 153. With this arrangement, it may readily be understood that, when the stop arm 156 is rocked away from the pawl heel 151c 15 and the stop abutment 155, the drive disc 143 will be free to rotate and the clutch pawl 151 will be released and thrown into clutching engagement with the toothed clutch member 150 by the spring 153. 20

Rotation of the main drive shaft 137 is thus effected for a single revolution, during which time the stop arm 156 is returned to its normal position so that, at the completion of such single revolution, the arm will first engage the pawl heel 151c to unclutch the pawl from the toothed clutch member 150 and will then engage the stop abutment 155 to arrest the disc 143 and its connected drive mechanism. The arm 156 thus not only acts as a releasable stop for arresting 30 the disc 143 at the completion of each revolution of the main drive, but also serves as a clutch-operating means.

The conveyer clutch C^e, which is shown in elevation in Fig. 10, comprises the toothed clutch member 150 carried by the power pulley 132, and a clutch pawl 151 associated with certain pawl operating means including a toothed disc 182 which is loosely mounted on the counter-shaft 133 between the conveyer drive sheave 144 and the toothed clutch member 150, as shown in Fig. 8. The clutch pawl 151 has a clutch tooth 151a which, as shown in Fig. 10, normally is in clutching engagement with the toothed clutch member 150, and is pivoted on a pivot screw 183 which 45 extends through a slot 184 in the toothed disc 182 and is screwed into the conveyer drive sheave 144, the clutch pawl 151 thus being carried directly by the sheave 144. Also carried by the sheave 144 and projecting through a slot 185 in 50 the disc 182 is a pin 186, and to this pin is attached one end of a spring 187, the opposite end thereof being attached to the clutch pawl 151. Another spring 188 is also attached to the pin 186 and to a pin 189 carried by the disc 182. The 55 clutch pawl 151 carries a stud 151c which projects into an angled cam slot 190 formed in the loose disc 182.

With this clutch mechanism in the normal condition shown in Fig. 10, it will be evident that 60 the toothed clutch member 150 will, through the engaged clutch pawl 151 and its pivot screw 183, drive the conveyer drive sheave 144, and that, during this driving function, the spring 188 will 65 yieldingly maintain the toothed disc 182 in an advanced rotary position with the rear end of the slot 185 engaging the pin 186 and the rear end of the slot 184 engaging the pivot screw 183, these slot ends thus limiting the advance throw of the disc 182. 70

Clutch control

For the purpose of controlling the two clutch devices D^e and C^e by the operation of the previously described envelope-operated control trip T^e, there is associated with these clutch devices 75

the following described mechanism which is clearly shown in Figs. 8, 10, and 11.

Projecting from the outer side of the counter-shaft drive disc 143 is a stud 200, and aligned with this stud so as to be engaged thereby is a cam lever 201 which is secured to a rock-shaft 202 journaled in bearings 134^c and 79^c on the respective standards 134 and 79. In Fig. 11 it will be noted that the stud 200 is normally in advance of the cam end of the lever 201 and that the lever is in an outer position with its cam end out of the path of said stud. Thus, the stud moves away from the cam lever when rotation of the drive disc 143 is initiated. However, with the initial operation of the control mechanism, the rock-shaft 202 will be rocked, as will presently be explained, to bring the cam end of the lever 201 into the rotary path of the stud 200 so that, near the end of a single driving cycle of the drive disc 143, the stud will engage the cam end of the lever 201 and cam the lever outwardly to rock the shaft 202 back to its normal position.

As shown in Figs. 8 to 10, there is secured to the inner end of the clutch-control rock-shaft 99 a trip finger 203 adapted to engage a wipe pawl 204 pivoted on the lower end of a floating stop lever 205, the upper end of the stop lever being provided with a nose 205^a aligned with the loose disc 182 and adapted to engage the teeth thereof. The lever 205 has a longitudinally disposed medial slot 205^b by means of which it is mounted to fulcrum on the rock-shaft 202 and to have a longitudinal bodily translation thereon limited in extent by the length of said slot. The wipe pawl 204 is provided with a spring 206 connected to the lever 205 and tending to yieldingly maintain the pawl in normal position with a stop-ear 204^a thereof engaging an edge of said lever to prevent movement of the pawl in one direction, said pawl having an abutment surface 204^c disposed substantially in the same direction as the slot 205^b in the stop lever 205 so as to readily slide free of the trip finger 203 when the stop lever is translated upwardly.

Secured on the shaft 202 adjacent the stop lever 205 is an arm 207 having a lateral ear 207^a extending across the longitudinal edge 205^b of lever, which is disposed substantially parallel with the slot 205^b so that arm will not be affected by the bodily translation of the lever 205.

Stud 200 is carried by the stop lever 205, and this stud extends into a slot 209^a formed in an arm 209 of a bell-crank lever 210 secured to the rock shaft 157 and having a depending arm 210^a which is slightly offset to engage the edge of the stop lever 205. As previously explained, the depressing of the trip lever T^r by an envelope will rock the clutch-control rock-shaft 99. The direction of this rocking movement of shaft 99 will be in a clockwise direction as viewed in Fig. 10, and by such movement the trip finger 203, by reason of its engagement with the wipe pawl 204, slightly oscillates the stop lever 205 to engage its nose 205^a with the teeth of the loose disc 182. This initial oscillation of the stop lever 205 will not rock the rock-shaft 157, due to the fact that the slot 209^a in the bell-crank arm 209 is concentric with the shaft 99, but it will immediately rock the rock-shaft 202 through the engagement of the edge 205^b of the stop lever with the ear 207^a of the arm 207, thus causing the cam arm 201, which is associated with the clutch device D^c, to be moved into the path of the stud 200 carried by the counter-shaft drive disc

143. With the engagement of the stop lever 205 with the teeth of the disc 182, that disc will, by reason of its rotation, bodily translate the stop lever 205 upwardly until the lower end of its slot 205^a engages against the rock-shaft 202, 5 whereupon the lever will arrest the forward rotation of the disc.

The continued rotation of the clutch pawl 181 will cause its stud 181^a to ride outwardly in the angled cam slot 190 in the now stationary disc 10 182 to withdraw the tooth 181^b of this clutch pawl out of driving engagement with the teeth of the constantly driven clutch member 158, thus unclutching the conveyer drive sheave 144 from the driving mechanism. During this unclutching operation, the pivot screw 183 of the clutch pawl 181 travels the length of the slot 184, while the pin 186 travels the length of the slot 185, this travel of the pin 186 tensioning the spring 188 so as to tension the toothed stop disc 182 and 20 maintain the stop lever 205 elevated with its nose 205^a in engagement therewith. During this unclutching of the conveyor clutch C^c, the upward translation of the stop lever 205 will, through the pin and slot connection 208—209^a, rock the 25 rock-shaft 157 to disengage the stop arm 156 of the main drive clutch D^c from the stop abutment 155 of the counter-shaft drive disc 143 and from the heel 151^a of the clutch pawl 151. This elevation of the stop lever also raises the wipe pawl 30 204 free from the trip finger 203. Immediately the spring 153 will throw in the clutch pawl 151 to engage its clutch tooth 151^a with the toothed clutch member 150 and thus establish the driving connection by which the power pulley 132 35 will drive the main drive shaft 137 through the counter-shaft 133 and the bevel gears 135 and 136.

With the conveyor drive thus unclutched and the drive to the metering printer M^p thus established, the drive disc 143 will make nearly one complete revolution when the stud 200 will have come into engagement with the cam arm 201 to rock the rock-shaft 202 back to normal position. This return of the rock-shaft 202, through the arm 207 and the engagement of its ear 207^a with the edge 205^b of the stop lever 205, will effect a return oscillation of the stop lever to disengage its nose from the teeth of the disc 180 and to rock the bell-crank 210, the stop lever thus 40 being lowered to its normal position through its pin and slot connection 208—209^a with the bell-crank, and the rock-shaft 157 thus being rocked to return the stop arm 156 of the clutch device D^c to its normal position, as shown in Fig. 11. 45 As the disc 143 completes its single revolution, the heel 151^a of the clutch pawl 151, which is now somewhat in advance of the stop abutment 155, engages the stop arm 156 to rock the clutch pawl 151 out of clutching engagement with the 50 toothed clutch member 158, the stop abutment then engaging the stop arm 156 to arrest the disc 143 and its connected driving train, including the counter-shaft 133, the power shaft 137, 55 and the connecting bevel gears 135 and 136. 60

When the stop lever 205 is released from engagement with the toothed disc 182, as above explained, the energy previously stored in the spring 188 will throw the released disc 182 forwardly and thereby cause the walls of its angled 65 cam slot 190 to act upon the stud 181^a this action of spring 188, assisted by spring 187 of clutch pawl 181 throwing in the clutch pawl and thus again establishing the driving connection from the power pulley 132 through counter-shaft 133 70 75

to the conveyor drive shaft 11. Since an envelope does not release the trip T^r until after the drive to the conveyer is re-established to cause the conveyer to translate the envelope past the upper end of said trip T^r , the stop lever 205 of the conveyer clutch C^c will be returned to its normal position, while the trip finger 203 remains in operated position. It is for this reason that the wipe pawl 204 is provided. As the stop lever 205 is rocked back and lowered while the trip finger is in tripped position, the wipe pawl 204 will contact the top end of the trip finger and be idly turned on its pivot against the tension of its light return spring 206; with a return of the trip finger, the wipe pawl will again drop in front of the trip finger to the normal position shown in Fig. 10.

There is thus provided a clutch control operated by each envelope fed through the machine and functioning to throw out the conveyer drive and momentarily arrest the conveyer as each envelope arrives at the printing station, and to throw in the main drive to effect operation of the printer through a single printing cycle while an envelope is at rest at the printing station, to print a stamp indicia thereon, the control further functions to throw out the main drive at the completion of each printing cycle of the printer and to throw in the conveyer drive to cause the conveyer to eject the printed envelope and continue the feed of the succeeding envelope toward the printing station.

In some instances it may be desired to use the machine merely as an envelope sealer. This specific use of the machine is made possible by reason of the manual means which, as previously mentioned, is associated with the trip lever T^r . That means, as shown in Figs. 1, 3, and 8, comprises a rod 220 journaled in suitable bearings carried by the respective outer and inner walls of the conveyer housing and having secured to its outer end exterior of the housing a manually manipulative knob 221 provided with an indicating stop finger 221^a adapted to alternatively engage two relatively spaced stop pins 222 carried by the housing, the stop pins serving to limit the rocking movements of the rod 220. Within the housing and adjacent the trip lever 97 is a trip disabling arm 223 having an upper horizontal end 223^a which projects in front of the terminal finger 97^a. Extending between the end 223^a and an anchor stud 224 secured to the machine base 50 is an overcenter spring means comprising an upper spring 225, a lower spring 225^a, and an intermediate bridging ring 225^c surrounding the rod 220.

To condition the machine to serve only as an envelope sealer, the knob 221 is turned in a counter-clockwise direction to cause the lateral upper end 223^a of the arm 223 to engage the terminal finger 97^a of the trip lever and rock it backwardly until its upper end is submerged below the table surface, the overcenter spring means of the arm being of sufficient tension to overcome the tension of the return spring 97^e of the terminal finger and maintain the terminal finger in this submerged position until released by a reverse operation of the knob 221.

With the terminal finger 97^a of the trip lever T^r thus submerged out of the path of the envelopes fed by the conveyer, the clutch control rockshaft 20 will not be rocked when the machine is operated and therefore the clutch devices D^c and C^c will remain in their normal condition, as shown in Figs. 10 and 11, so as to effect a continuous drive of the conveyer while the main drive shaft 131,

which, in other instances, provides the drive means for the metering printer unit, remains idle. Thus, the machine may be conditioned for operation to continuously feed, moisten, and seal envelopes and eject the sealed envelopes from the machine; and, since the drive for the metering printer M^p remains idle during such operation of the machine, the machine may be employed for this specific use either while the metering printer unit M^p is associated with the machine or while it is removed from the machine.

With the envelope-operated trip T^r in operative condition and the metering printer unit in operative position, the machine may feed and print upon envelopes which have previously been sealed by other means. In this use of the machine, the moistener will continue to operate, but it and the sealer will remain functionally idle since there will be no open envelope flaps to be moistened and sealed.

The machine, as thus far described, incorporates in a unitary structure a base for supporting the various mechanisms and their enclosing housings; a table along which envelopes are translated singly and in succession while horizontally disposed with their open flaps extended downwardly over an edge of the table; a hopper associated with said table and adapted to contain a stack of horizontally disposed envelopes having their open flaps depending in shingled relation, and provided with yielding baffle means insuring the withdrawal therefrom of only one envelope at a time; a suction or vacuum conveyer associated with the table and functioning to grip and withdraw the envelopes singly and in succession from the bottom of the stack of envelopes within the hopper and to translate said envelopes along the table to a printing position or station; a flap moistening device of the atomizing type adapted to moisten the flaps of the envelopes as they are fed along the table; an envelope sealing means for closing the moistened envelope flaps; a support for receiving a removable printing unit having a printing means above the table at the printing station positioned to print upon the envelopes; a means for supplying fluid to the atomizer; pump means for supplying air under pressure to said atomizer and for creating and maintaining a suction or vacuum in the conveyer; a means whereby the degree of suction or vacuum may be regulated; driving mechanism comprising a power element constantly driving said pump means, a main drive element for driving the printer unit, a conveyer drive means and clutch mechanism. The clutch mechanism comprises a drive clutch between the power element and the main drive and a conveyer clutch between the power element and the conveyer drive means, the clutches being arranged for automatic correlated action; and envelope-operated trip means.

The trip means functions to control the clutches in such a manner as to provide an alternate drive of the conveyer and of the printing unit whereby the printing unit remains idle while the conveyer is translating an envelope to the printing station and the conveyer is stopped while the printer is operated through a single printing cycle to print upon the momentarily stationary envelope, after which the conveyer drive is re-established to cause an ejection of the printed envelope and a continuation of the feed of the succeeding envelope, the printer remaining idle until such succeeding envelope arrives at the printing station. The machine also includes manually operated means for

disabling the envelope-operated clutch control trip means when it is desired to condition the machine for use only as an envelope sealing means.

It will be noted that the hopper is devoid of an outer side wall and is so associated with the table as to provide a discharge throat which is open at its outer end so that the machine will be adapted to handle envelopes of various widths, very wide envelopes being permitted to overhang the outer side edge of the table. It will be understood that, while the machine is herein described in detail in connection with the handling of envelopes, it is also adaptable for use in the printing of cards, tickets, or other articles of the same general character.

Metering printer unit

As best shown in Figs. 12 to 16, this unit provides a two-part structure including a relatively stationary base member 300 carrying the impression platen P^1 , an oscillatory head 301 containing a printing mechanism P^r arranged to cooperate with said platen, a total register R^e , a metering register M^e , and associated operating mechanisms.

The base member 300 has a rear wall 302, a front wall 303 having a forwardly projecting shelf 303^a serving as a support for the impression platen, and opposite connecting side walls 304 and 305. The platen is provided with an insert of rubber or other material suitable to provide a resilient impression surface, and is mounted upon compression springs 306 supported upon the shelf 303^a so as to yield vertically under abnormal printing pressures due to printing upon relatively thick envelopes, or the like. The platen is slidably retained in place by a retaining member 307 which embraces the platen and is secured to the shelf 303^a by screws 308 and which provides stop shoulders 309 disposed for engagement by ears 310 on the platen so as to limit upward movement of the platen under influence of the cushioning springs 306. Disposed behind the impression platen and journaled in bearings 311 in the respective side walls 304 and 305 of the base member 300 is a transverse printer actuating shaft 312, and journaled in bearings 313 in the rear upwardly projecting portions of the respective side walls 304 and 305 is a transverse cam shaft 314.

The oscillatory head 301 includes a housing providing opposite side walls 315 and 316 forming supporting side frames for the interior mechanisms, and connecting rear, top, and front walls, 317, 318, and 319, respectively, the front wall 319 being of semi-cylindrical form to provide a barrel-like enclosure for the printing mechanism.

As shown in Figs. 15 and 16, the side wall 316 of the head 301 is disposed inside of and closely adjacent the side wall 305 of the base member 300 so as to have an overlapping relationship therewith, the opposite side wall 315 has an offset portion 315^a disposed in overlapping relationship to the side wall 304 of the base member and spaced inwardly therefrom to provide an intermediate space for accommodating a driving connection between the cam shaft 314 and the printer actuating shaft 312. This driving connection comprises a sprocket 320 fixed on the cam shaft 314, a similar sprocket 321 fixed on the printer actuating shaft 312, and a connecting sprocket chain 322. The sprockets are of the same size, providing a one to one driving ratio so that the printer actuating shaft 312 will rotate in unison with the cam shaft 314. To prevent tampering

with the interior mechanism, there is provided a guard apron 323 (see Figs. 15 and 16) attached to the side wall 316 of the head 301 and overlapping the side wall 305 of the base member 300, and a cover plate 324 attached to the side wall 315 of the head 301 and overlapping the side wall 304 of the base member.

Both side walls 315 and 316 of the oscillating head are journaled on the cam shaft 314 which thus serves as a means for hingedly supporting the head on the stationary base member so that the head may be oscillated relative thereto; the means for effecting such oscillation comprises duplicate actuating connections between the respective side walls of the head, and the shaft 312. Each of the connections includes an arm 325 depending from the respective side wall of the head and provided with an elongated slot 325^a embracing the shaft 312 and formed concentric with the axis of the cam shaft 314, a cam roller 326 mounted on the lower end of said arm, and a printer actuating cam 327 secured to the shaft 312 in position to engage the cam roller. Compression springs 328, interposed between the stationary base member 300 and a cross-bar 329 secured to the opposite side walls of the head, function to yieldingly maintain the head in normal elevated position with the cam rollers 326 engaging their respective actuating cams 327.

With this arrangement it will be obvious that, as the shaft 312 is rotated, the cams 327 acting upon the cam rollers 326 will cause the head 301 to be oscillated in a definite sequence in accordance with the specific contour of said cams.

Printing mechanism

The mechanism for printing the desired stamp indicia is mounted within the forward barrel-like portion of the oscillatory head which overhangs the impression platen P^1 and the table T^a along which the envelopes are fed. As most clearly shown in Figs. 12 to 15, this mechanism includes a relatively stationary printing stamp 330 adapted to print upon an envelope a designation of the mailing post office, the mailing date, and the user's meter-mail permit number, as indicated at X in Fig. 23, and a printing drum 331 carrying a plurality of individual printing members or electroplates 331^a (Figs. 13 and 15) adapted to be brought singly to printing position by pre-selective rotation of said drum to print a suitable stamp background, a meter number, and a prepaid postage value, as indicated at Z in Fig. 23, each electroplate of the series being capable of printing a postage value different from that printed by the others of the series, thus providing a multi-denominational printing element having a plurality of printing members of different denominations adapted to be pre-selectively set to a printing position.

A bracket 332 is secured to the upper portion of the side wall 315 and has a depending leg 332^a carrying the stationary stamp 330, the body of the stamp being laterally slidably in ways formed in said leg (see Fig. 14) so as to be capable of being removed from the machine when it becomes necessary to change the date printing type 330^a which are removably retained in place in the stamp body by a suitable set screw 330^c (see Fig. 15). The body of the stamp 330 is also provided with a shallow recess adapted for engagement with a spring pressed retaining ball 332^c tending to maintain the stamp in proper operative position and is further provided with a screw-threaded bore 330^e into which a suit-

able tool may be engaged for the purpose of removing and reinserting the stamp.

As best shown in Figs. 8 and 15, the cover plate 324 of the head 301 is provided with a 5 door opening 324^a normally closed by a swinging door plate 324^c and disposed in alignment with the stationary stamp 330. In removing the stamp 330 to change the date printing type 330^a, the operator opens the door 324^c, inserts through the 10 door opening 324^a a suitable screw-threaded tool, as indicated in dotted lines in Fig. 15, screws the tool into the threaded bore 333^c of the stamp, and withdraws the stamp outwardly through the door opening. The operator may then loosen 15 the set screw 330^b to release the type 330^a and, after replacing the type with others suitable to print a different date, replaces the stamp in the machine. A font of date type is preferably contained in a type drawer 34^b disposed as shown in 20 Fig. 1.

The several individual electroplates or printing members 331^a are disposed on the periphery of the printing drum 331 at uniform circularly spaced intervals, the preferable manner of securing these members in place being to press them in respective longitudinal grooves formed in the drum, as shown in Fig. 13, so as to be capable of being conveniently removed for repair or for replacement by new electroplates of the 25 same denominations or electroplates of different denominations when it is desired to change one or more of the denominations to be printed by the machine. The printing drum is secured on a drum shaft 335 which is rotatably journaled in bearings 335^a disposed in the respective side walls 315 and 316 of the head and in a bore formed in the leg portion 332^a of the stationary stamp supporting bracket 332, as shown in Figs. 12 and 15; adjacent the side wall 315 the shaft 335 has secured thereon a ratchet 336 which is 30 engaged by a pawl 337 pivotally mounted on the side wall, so that the shaft 335 and the printing drum may be rotated only in a clockwise direction, as viewed in Figs. 13 and 14.

45 Indexing means

Secured to the outer surface of the side wall 316 and disposed concentric to the axis of the drum shaft 335 is a wear ring 338, and formed 50 in this ring and in the adjacent side wall is a series of indexing holes 339 circularly spaced to coincide with the spacing of the printing members 331^a on the printing drum 331.

Adjacent the wear ring 338 and radially aligned 55 with the respective indexing holes 339 there are provided denomination indicators 340, each bearing a different postage value indication. These indicators preferably consist of individual plates provided with tangs 340^a (see Fig. 15) which 60 extend through suitable apertures in the side wall 316 and have their inner ends clinched over to retain the respective indicators in place, the indicators thus being conveniently removable for replacement by other indicators of different 65 denominations whenever any of the printing members 331^a have been replaced by others of different denomination.

The drum shaft 335 extends beyond the side wall 316 and has secured to it an indexing arm 70 341, the outer end of which carries an axially slidtable indexing pin 342 disposed in circular alignment with the several indexing holes 339 so as to engage in any one of said holes when brought into registry therewith. The indexing pin 342 has a knob 342^a fixed to its outer end

and is provided with a spring 343 tending to urge the pin inwardly against the wear ring 338 and into engagement with a selected one of the indexing holes 339.

In the pre-selective setting of the printing 5 drum to bring the desired printing member to printing position, the operator pulls outwardly on the knob to withdraw the indexing pin 342 and then rotates the indexing arm 341 in a clockwise direction to a new selected indexing position. Upon arriving at such new position, the indexing pin is allowed to be forced inwardly by its spring to engage in the appropriate indexing hole 339. However, the more natural method is to release the outward pull on the 10 knob somewhat before the new indexing position is reached to allow the indexing pin to 15 gradually engage the wear ring 338 and to automatically snap into the respective indexing hole as the indexing arm reaches the selected position, it being for this reason that the wear ring 20 is provided.

In the particular embodiment herein disclosed there are eight of the individual printing members spaced 45 degrees apart around the periphery of the printing drum and having stamp indicia capable of printing postage values of eight different denominations, including 1/2 cent, 1 cent, 1 1/2 cents, 2 cents, 4 cents, 5 cents, 10 cents, and 15 cents, the printing faces of three of these 30 being shown in Fig. 15. As shown in Fig. 1, there are eight of the indexing holes 339 and eight of the denomination indicators 340 respectively corresponding in value to the eight printing members. However, it is to be understood 35 that, by substituting other printing members and indicators of other denominations, the machine may be conditioned to print any desired series of postage values. It will also be understood that, while the disclosed embodiment is designed to 40 print stamps of eight different denominations, the machine may be constructed to print a less or a greater number of denominations, that being merely a matter of design and size of the machine.

45

Interlock

For the purpose of locking the indexing mechanism against movement while the printing mechanism is in operation and for locking the 50 printing mechanism during pre-selective indexing, there is provided an interlock mechanism between the cam shaft 314 and the printing drum shaft 335. This interlock is best shown in Fig. 13, and includes a lock-plate 345 mounted in fixed 55 relation to the shaft 335, preferably by being attached to the side of the drum 331 by screws 345^a, a lock-disc 346 secured to the cam shaft 314, and an associated lock-bar 347. The lock-bar 347 is provided with an elongated slot 347^a embracing the cam shaft 314 and has a bifurcated forward end providing opposite furcations 347^c engaging the hub of the printing drum 331, the furcations and elongated slot being relatively aligned so that the lock bar is slidably supported 60 upon the drum hub and the cam shaft. The lock-plate 345 is provided with eight lock recesses 345^b formed at equally spaced intervals around its periphery and adapted to be singly engaged by an anti-friction roller 347^e mounted on the 65 lock-bar 347; adjacent the lock-disc 346 the bar 347 is provided with a laterally projecting lock-stud 347^s adapted to engage in a lock notch 346^c formed in the periphery of the lock-disc in position to be normally aligned with the lock-stud. 75

The rear end of the lock-bar 347 is in alignment with the upper end of an arm 348 which is secured on a transverse rock shaft 349 journaled in the respective side walls of the base member 399, and secured to this rock shaft 349 is a depending arm 350, the lower end of which is provided with an elongated slot in which engages a pivot pin 351 carried by the rear end of a push rod 352. This push rod is slidably supported at 10 its forward end in a bore in the platen-retaining member 307 and is so disposed that it may be projected into the path of movement of the previously described envelope-operated trip lever 97. A spring 353 is connected to the depending 15 arm 350 and to the rear wall 302 of the base member 399, and serves to yieldingly maintain the several parts of this interlock in the normal positions shown in Fig. 13.

With these parts so disposed, it will be apparent 20 that, when the indexing pin 342 of the manually operable indexing arm 341 is engaged in one of the indexing holes 339, one of the individual printing members 331^a will be at the printing position and the lock-bar 347 will be in its 25 forward position with its anti-friction roller 347^e in an appropriate one of the lock recesses 345^e of the lock-plate 345, and that, as the printing drum 331 is rotated in an indexing operation, the roller 347^e will successively engage the outer periphery 30 and the succeeding lock recesses 345^e of the lock-plate 345. Thus, whenever the printing drum is being rotated from one indexed position to another, the lock-bar 347 is pushed rearwardly to 35 engage its lock stud 347^s in the lock notch 346^c of the lock-disc 346 and, in this manner, lock the operating cam-shaft 314 against rotation, the lock-bar 347 also rocking the arms 348 and 350 to project the push-rod 352 into the path of movement of the envelope-operated clutch-control lever 97 to prevent the establishment of a driving connection between the power means and the cam shaft 314. Also, with the printing drum in a selected indexed position, lock-stud 347^s on lock-bar 347 is removed from the lock-notch 346^c 40 of the lock-disc 346 by the forward movement of the lock-bar through rocking of arm 348 by spring 353; rotation of the cam shaft 314 in a printing operation will remove the lock-notch 346^c of the lock-disc 346 from registry with the lock-stud 347^s and bring the unbroken portion 45 of the periphery of disc 346 opposite the stud to form an abutment preventing rearward translation of the lock-bar 347, thus preventing a manual indexing of the printing drum during a 50 printing operation.

This arrangement renders it impossible to effect a pre-selective manual indexing while the printing mechanism is operating and permits a 55 printing operation only at such times as the printing drum is latched in one of its pre-selected positions.

Printer guard

To prevent a fraudulent taking of an impression 60 from the printing means, there is provided a printer guard which, as best illustrated in Figs. 13 to 15 and 24, comprises a clevis-like member consisting of a depending arm 360^a disposed at one side of the stationary stamp 330, a depending arm 360^c disposed on the opposite side 65 of the drum 331, both of said arms being loosely journaled on the drum shaft 335, and an arcuate shield 360 joining the lower ends of said depending arms and disposed between the face of the drum and the front wall 319 of the head.

Normally, this shield 360 is in the position shown in Figs. 13 and 14 to, in effect, form a movable continuation of the front wall 319 of the head, and serves to defeat any attempt to secure an impression from the printing members while the 5 head is in an elevated position.

During each operative cycle of the cam shaft 314, the shield 360 is oscillated forward and back during the inking of the printing surfaces; it is again oscillated forwardly during a printing oscillation of the head, and then returned to normal position as the head is elevated to its normal position. To effect this oscillation of the shield, its arm 360^c is provided with a bell-crank extension 360^e to which is pivotally connected 10 a long lever 361 which extends rearwardly above the cam shaft 314 and is pivotally journaled on a cross-rod 362 disposed rearwardly of the cam shaft and carried by the opposite side walls of the head (see Figs. 12 and 24). Above the cam 20 shaft 314 the lever 361 carries a cam-roller 363 which engages a shield operating cam 364 fixed on the cam shaft; to maintain the cam-roller 363 in contact with cam 364, there is provided a contractile spring 365 connected to the lever 361 and 25 to a cross-rod 366 carried by the opposite side walls of the head.

Inking mechanism

This mechanism is clearly shown in Figs. 12 to 30 15 and includes a rotary ink supply reservoir 370 carrying an arcuate ink pad 370^a, an inking roller 371, and suitable operating connections whereby the inking roller will receive ink from the ink pad as it is rotated and will be then oscillated 35 across the printing members at the printing position to ink the printing surfaces thereof. The reservoir 370 is secured to the intermediate portion of the printer actuating shaft 312 between the two previously described printer actuating 40 cams 327, as shown in Fig. 15, and comprises a barrel-like structure adapted to contain a body 370^c of fluid ink. The circumferential wall of the reservoir is formed to provide outwardly projecting longitudinal flanges 370^e circularly spaced 45 from each other and joined by a perforated wall 370^s. The ink pad 370^a, formed of felt or other suitable absorbent material, is secured on the perforated wall between the flanges 370^e and provides an arcuate ink distributing surface radially 50 disposed beyond the mean diameter of the main cylindrical portion of the reservoir.

As the shaft 312 is rotated in unison with the cam shaft 314 by the sprocket and chain connection 320, 321, 322 (see Figs. 14 and 15), the ink supply reservoir 370 will be driven one complete revolution during each operative cycle of the printing mechanism to submerge the perforated wall 370^s thereof below the body 370^c of 60 ink; during such submergence the ink pad 370^a will absorb sufficient ink through the perforations of wall 370^s to become properly saturated for a subsequent inking operation.

The inking roller 371 is mounted upon a shaft 65 which extends beyond the opposite ends of the roller to provide trunnions 371^a (see Fig. 15) and these trunnions engage respectively in elongated slots 371^c formed in respective depending arms 372 and 373, which are loosely journaled on the 70 drum shaft 335 and have their lower end portions connected to each other by a transverse tie-rod 373^a riveted thereto. Each of the arms 372, 373 is provided with a stud 371^c and connected to each of these studs and to the adjacent 75

trunnion of the inking roller is a contractile spring 371^c. These springs tend to yieldingly maintain the inking roller in its uppermost position with its trunnions engaged in the upper 5 portions of the elongated slots 371^c. With particular reference to Figs. 12 and 14, it will be observed that the depending ink roller supporting arm 372 is provided with a bell-crank extension 372^a, to which is pivotally connected a 10 long lever 374 which extends rearwardly above the cam shaft 314 and is pivotally journaled on the cross-rod 362. Above the cam shaft 314 this lever 374 carries a cam-roller 375 which engages an ink roller operating cam 376 fixed on the cam 15 shaft; to maintain cam-roller 375 in contact with cam 376, there is provided a contractile spring 377 which connects to lever 374 and to the cross-rod 366. This mechanism functions to oscillate the inking roller 371 forward and back once during each operative cycle of the cam shaft 314 and in a certain timed sequence in relation to the 20 operations of the printer shield 360 and the oscillatory head.

A removable pan 378 closes the opening in the 25 base member in which the ink reservoir 370 is disposed; to permit replenishing of the ink supply, the reservoir is provided with a filling opening 379 normally closed by a screw-threaded plug 380. With the reservoir in normal position, the 30 plug 380 will be disposed opposite an opening 378^a in the pan 378; when a replenishing of the ink supply becomes necessary, the unit M^p will be removed from the machine and turned upside down, the plug 380 being removed by means of a 35 suitable tool inserted through the opening 378^a, and the reservoir 370 then being refilled in any suitable manner, after which the plug 380 will be replaced to seal the reservoir against leakage.

Printing operation

Assuming that the printing drum has been 40 selectively set by the manual indexing means 341, 342, 342^a (Figs. 1 and 15) to bring to the printing position a stamp indicia printing member 331^a of the desired denomination, and that an envelope is upon the impression platen Pⁱ in position to receive a printed impression, a complete 45 inking and printing cycle will be effected during one revolution of the cam shaft 314 and the printer actuating shaft 312 rotated in unison therewith.

Rotation of the cam shaft 314 immediately 50 move the lock-notch 346^c out of registry with the lock-stud 347^s of the interlock bar 347, thus preventing any manual operation of the indexing 55 mechanism during the printing cycle. As the printer actuating shaft 312 is rotated to revolve the ink supply reservoir 370, the arcuate ink-saturated pad 370^s passes beneath the inking 60 roller 371 and, by pressurable contact therewith, rotates the roller and causes a uniform distribution of ink thereon, after which the pad passes from contact with the roller and by continued rotation of the reservoir is subsequently brought 65 again to the normal position shown in the drawings. During this ink-distributing contact of the reservoir pad with the inking roller, the inking roller 371, the printer shield 360, and the oscillating head 301, all remain in their respective 70 normal positions, due to the positions of their respective operating cams. Throughout this period in the operating cycle, the cam-roller 375 of the inking roller actuating lever 374 is in engagement 75 with the outer concentric portion of the ink roller

actuating cam 376; the cam-roller 363 of the printer shield actuating lever 361 is in engagement with the concentric portion 364^a (see Fig. 24) of the guard actuating cam 364; and the cam-rollers 326, carried by the oscillating head side 5 walls, are in engagement with the concentric portions 327^a (see Figs. 13 and 14) of the head actuating cams 327 which rotate with the shaft 312.

After the ink pad has passed from engagement with the inking roller, it is desired to elevate the 10 oscillating head while the inking roller is oscillated forwardly to ink the printing members, so that the roller will not contact or brush over the envelope which is upon the impression platen; it is also necessary to oscillate the printer 15 shield forwardly out of the path of the inking roller while the printing members are thus being inked. To accomplish this, the actuating cams 327 have inclined drop portions 327^b which, in passing the cam-rollers 326, permit the head 301 20 to rise under the influence of the springs 328, while a gradual drop 376^a (see Fig. 14) in the periphery of the inking roller actuating cam 376, arriving at the cam-roller 375 of the inking roller actuating lever 374, permits the spring 377 25 to oscillate the inking roller 371 forwardly across the printing surfaces of the stationary stamp 330 and the printing member 331^a which is disposed at the printing position. While this forward oscillation of the inking roller is taking place, a 30 gradual drop 364^a (see Fig. 24) in the periphery of the printer shield actuating cam 364, arriving at the cam-roller 363 of the shield actuating lever 361, permits the spring 365 to oscillate the printer 35 shield 360 out of the path of the inking roller.

Continued rotation of the cam 376 causes a rise 376^c thereof to immediately cam the cam-roller 375 upwardly to effect a return oscillation of the inking roller 371 to normal position, the inking roller remaining in such normal position 40 during the balance of the operating cycle. While the inking roller 371 is thus returning to its normal position, it is followed by the printer shield 360 by reason of the fact that the cam-roller 363 of the shield actuating lever 361 will be engaged 45 and cammed upwardly by a rise 364^c of cam 364 until the shield is returned to its normal position.

When the printing surfaces are thus inked, the 50 shaft 312 will have been rotated sufficiently to bring a rise 327^a of each head oscillating cam 327 in front of the respective cam-roller 326 so that continued rotation of the shaft will effect a downward oscillation of the head to pressurably 55 engage the inked printing surfaces with the envelope to print thereon the pre-selected stamp indicia.

Since the printer shield must be moved from the path of oscillation of the printing members before they can engage the envelope, the shield 60 360 is given a second forward oscillation during the downward oscillation of the head 301. To effect such second oscillation of the shield, the shield actuating cam 364 is provided with a gradual drop 364^a so timed in relation to the 65 downward oscillation of the head as to cause the shield 360 to fully clear the printing surfaces just before they contact the envelope.

After the printing of the envelope, the head is 70 elevated to normal position by the springs 328 as the respective cam-rollers 326 engage the gradually inclined portions 327^b of the respective head actuating cams 327, while the printer shield is returned to normal position by the shield actuating lever 361 which is elevated by engagement 75

of its cam-roller 363 by a rise portion 364^s of the cam 364.

Metering or descending register

5 In a suitable opening formed in the top wall 313 of the oscillatory head (see Fig. 13) is hingedly mounted a door 400 having a sunken window 400^a, preferably of glass, permitting observation of the metering register M^e. Mounted in the 10 door, adjacent the free edge thereof, is a key lock 400^c having a swingable sealing plate 400^e adapted to be secured in position by a suitable wire and lead seal 400^s to prevent access to the lock.

The register M^e is disposed immediately below the window 400^a. In the present embodiment (see Fig. 16), this register provides a series of six meter wheels including a fractional cent wheel 401, a cents wheel 402, a dimes wheel 403, a dollars wheel 404, a ten dollars wheel 405, and a 15 hundred dollars wheel 406, all of which are mounted to rotate freely on a stationary shaft 409 secured in the opposite side walls 315—316 of the head. As shown in Figs. 16 and 17, all of these meter wheels, excepting the fractional cent 20 wheel 401, are provided with ten indicia including digits from one to nine, and zero, these indicia being serially arranged in such manner that, as the meter is operated, they successively appear at the window 400^a in the reverse order 25 0, 9, 8, 7, etc.; the fractional cent wheel 401 is, as shown in Fig. 16, provided with ten indicia including five zero indicia and five fractional indicia of one-half cent value arranged so that the zero and fractional indicia will appear singly in alternate sequence at the window. This 30 meter is thus enabled to function as a descending or subtracting register capable of registering not only dollars and cents but also fractional 35 cent values.

40 While the indicia of the fractional cent wheel will preferably be of a color distinctive from the indicia of the other meter wheels, so that its zero indicia may always be understood to mean—no fraction of a cent—, this zero indicia could be 45 eliminated, leaving blank spaces between the several fractional indicia, which could then be of the same color as the indicia of the other wheels without causing any confusion. It will also be obvious that the decimal system could 50 be employed by using, in place of the fractional indicia ½, the figure 5 to indicate five-tenths of a cent.

The mechanism associated with the fractional cent wheel 401 (see Fig. 17) includes a stationary 55 inner sleeve 410 which is provided near its inner end with a radial flange 411 and has mounted on its outer end a retaining collar 412, the sleeve and collar being fixed to the stationary shaft 409 by a pin 413 extending therethrough. Rotatably 60 mounted on this inner sleeve 410 is an outer sleeve 414 having at its outer end a radial flange to which is secured, by rivets as shown in Fig. 17, or by other suitable means, the transverse wall of the meter wheel 401 and an adjacent carry-over disc 65 415. In the present embodiment this disc is formed of a pair of plates, the outermost of which is provided with a concentric series of ten ratchet teeth 416 (see Fig. 20) stamped and bent outwardly from the body of the plate and uniformly 70 spaced about the axis of the shaft 409. The transverse wall of the meter wheel 401 is provided with a similar concentric series of ten ratchet teeth 417. As shown in Fig. 21, the ratchet teeth of both series face in the same 75 rotary direction.

Riveted or otherwise secured to the flange 411 of the sleeve 410 is a ratchet disc 418 of spring metal formed to provide two diametrically opposite yieldable ratchet fingers 419, which are concentrically disposed and are bent in an axial 5 direction so as to have a continuous yielding engagement with the ratchet teeth 416 of the carry-over disc 415. A similar ratchet disc 420 provides two diametrically opposite ratchet fingers 421 bent inwardly to yieldingly engage the 10 ratchet teeth 417 of the register wheel 401. This ratchet disc 420 is attached to a meter actuating gear pinion 422 which is rotatably journaled on the outer sleeve 414, the preferable manner of attachment being to provide the disc 420 with 15 pairs of laterally projecting ears 423 which engage on opposite sides of certain of the teeth of the pinion 422, as shown in Figs. 19 and 21.

The mechanisms associated with the next two meter wheels, 402 and 403, are of duplicate construction; and since the parts thereof are, excepting as will be specifically pointed out, exact duplicates of the similarly disposed parts associated with the above described meter wheel 401, these parts will merely be designated by similar 20 reference numerals with the suffix "a" added thereto and only such differences as may exist 25 will be described in detail.

One of such differences resides in the fact that in each of the mechanisms associated with the respective meter wheels 402 and 403, the inner sleeve 410^a, instead of being fixed to the shaft 409 and provided with a retaining collar, is loosely journaled to rotate on the shaft, and has secured to its outer end a large transfer gear 30 424^a. Another specific difference resides in the particular construction of the respective carry-over discs to cooperate with the Geneva transfer means to be later described.

The meter wheels 404, 405, and 406 are all 40 of duplicate construction, each including a sleeve or hub 414^a provided with a radial flange to which the respective meter wheel and adjacent carry-over discs 415^a are secured, and having secured to its opposite end a large transfer gear 424^a. 45

The carry-over disc 415 which is carried by the fractional cent meter wheel 401, has cut in its periphery five equally spaced tooth recesses 425, as shown in Fig. 20, and secured to the side of said disc are five Geneva tooth blocks 426, 50 each disposed adjacent one of the tooth recesses and providing two transfer teeth disposed on opposite sides thereof. As shown in Fig. 18, each of the carry-over discs 415^a, carried respectively by the cents meter wheel 402 and the dimes meter 55 wheel 403, has only one tooth recess 425^a and one Geneva tooth block 426^a, while each of the carry-over discs 415^a, associated respectively with the meter wheels 404, 405, and 406 is likewise provided with only one tooth recess 425^a and 60 one Geneva tooth block 426^a, as shown in Fig. 17.

As shown in Figs. 13 and 17, a transverse rod 430 is disposed somewhat above and rearwardly of the meter wheels, this rod being mounted in 65 the opposite side walls 315—316 of the oscillatory head and having journaled thereon two bellcranks 431, the lower arms of which carry a transfer pinion shaft 432. Mounted to rotate freely on this pinion shaft is a series of transfer 70 pinions 433 which are, by suitable spacing sleeves, maintained so axially spaced from each other that each of the pinions may co-operate with the carry-over disc of one of the meter wheels and mesh with the large transfer gear of the meter 75

wheel of next higher denomination in the order shown in Fig. 17. Each transfer pinion 433 has an even number of long teeth 433^a and alternating short teeth 433^c, all of which mesh with the associated large transfer gear, the long teeth 433^a extending over the carry-over disc of the meter wheel of next lower denomination so that two adjacent long teeth normally engage the unbroken periphery of the carry-over disc to lock the transfer pinion, the transfer gear, and connected parts, against rotation until a transfer is to be effected, while the short teeth 433^c extend only far enough to be engaged by the Geneva teeth of the carry-over disc. With a transfer pinion 433 in normal position, as shown in Fig. 18, one of the short teeth 433^c thereof will be in the path of the Geneva tooth block 426^a; and, when a transfer is to be effected, the block will engage this short tooth to rotate the transfer pinion, the succeeding long tooth 433^a meshing into the tooth recesses 425^a of the carry-over disc to continue the drive of the pinion until it is rotated a distance of two teeth, in a manner usual in this type of Geneva transfer mechanism. This two tooth transfer rotation of any one of the transfer pinions 433 will rotate the associated transfer gear a distance of two teeth; and, since each transfer gear has twenty teeth, it will thus be rotated one-tenth of a revolution to transmit the proper transfer movement to the meter wheel of next higher denomination.

Obviously, since the fractional cent meter wheel 401 is rotated one-tenth of a revolution for each one-half cent value, it becomes necessary to effect a one-cent transfer to the cents meter wheel 402 for every one-fifth revolution of said fractional cent meter wheel; therefore, the carry-over disc 415 requires the five Geneva tooth blocks 426 and the five associated tooth recesses 425 disposed as shown in Fig. 20.

The first three meter wheels are actuated by three actuating gear sectors including a fractional cent sector 500 which meshes with the actuating pinion 422 of the fraction cent meter wheel 401, a cents sector 500^a which meshes with the actuating pinion 422^a of the cents meter wheel 402, and a dimes sector 500^b which meshes with the actuating pinion 422^b of the dimes meter wheel 403.

These sectors are, by suitable means which will later be described, successively oscillated forwardly (with reference to Fig. 13) different distances, depending upon the pre-selected stamp value for which the machine is set, and then are progressively returned to their respective normal positions; since it is an important feature of the present invention that the registers remain in constant engagement with their actuating means, instead of having to be disengaged therefrom during each operation of the machine, as is necessary in certain machines heretofore proposed, it is necessary to provide an intermediate ratchet mechanism so arranged as to cause rotation of the meter wheels only when their actuating pinions are rotated in one direction. It is for this reason that the above described ratchet connections are provided, and, in a metering operation, these ratchet connections will function in the following manner.

The inner sleeve 410 of the fractional cent wheel assembly, being fixed to the stationary meter shaft 409, maintains the ratchet disc 419 stationary so that its ratchet fingers 419 will, by their engagement with the ratchet teeth 416 of the carry-over disc 415, prevent retrograde

rotation of the meter wheel 401 in a clockwise direction, as viewed in Fig. 13. As viewed in Fig. 13 and also in Fig. 19, a forward oscillation of the actuating sector 500 will effect a clockwise or backward rotation of the actuating pinion 422 which carries the ratchet disc 420, and, during such backward rotation, the ratchet fingers 421 will ratchet idly over the ratchet teeth 417 of the meter wheel 401. In this manner, the meter wheel 401 will remain stationary during the forward oscillation of the actuating sector 500 and the forward or clockwise rotation of the actuating pinion 422, the ratchet fingers 421 driving the meter wheel 401 only during a return oscillation of the sector 500.

Similarly, the cents meter wheel is driven by the sector 500^a through the actuating pinion 422^a and its associated driving ratchet means 420^a, 421^a, 417^a, and is prevented from retrograde rotation by the ratchet means 418^a, 419^a, 416^a, since the inner sleeve 410^a is normally maintained stationary through its transfer gear 424^a and associated transfer pinion 433 by reason of the engagement of two of the long teeth 433^a of said pinion with the unbroken periphery of the carry-over disc 415 of the fractional cent meter wheel 401. In effecting a transfer from the wheel 401 to the wheel 402, the carry-over disc 415 will, through the associated transfer pinion 433 and the transfer gear 424^a on the inner sleeve 410^a of the cents meter wheel 402, rotate sleeve 410^a one-tenth of a revolution, thus causing the ratchet means 418^a, 419^a, 416^a to rotate the meter wheel 402 forwardly a distance of one unit to subtract one cent from the total previously registered on that meter wheel.

The ratchet mechanism associated with the dimes meter wheel 403 functions in the same manner as does that which is associated with the cents meter wheel 402, while the succeeding meter wheels 404, 405, 406 are devoid of any ratchet mechanism and are connected only by the simple Geneva transfer mechanism whereby each wheel will be rotated one-tenth of a revolution for each complete revolution of the meter wheel of next lower denomination.

In Fig. 17 it will be noted that the last transfer pinion 433, which receives the transfer movement of the carry-over disc 415^c of the last meter wheel 406, meshes with a transfer gear 424^c which is secured to the hub of a disc 434 loosely journaled on the meter shaft 409. This disc forms a part of a locking mechanism which will later be described.

As shown in Figs. 13, 14, and 17, contractile springs 435 are attached to the lower ends of the respective bell-cranks 431 and to a stationary cross-bar 435^a, and each bell-crank has an upwardly and rearwardly extending arm 431^a which normally engages the under surface of the closed door 400. By this arrangement the transfer pinions 433 will be maintained in proper engagement with the transfer gears and carry-over discs of the meter as long as the door 400 remains closed; however, when the door is opened, the bell-cranks will be rocked by the springs 435 and thus withdraw the transfer pinions 433 from such engagement so as to free the meter wheels for manual re-setting.

Pivotedly mounted on the rod 430 is an aligning bail comprising opposite arms 436 journaled on the rod and a connecting cross-bar 437 which normally engages between adjacent teeth of all of the transfer pinions 433. To one of the arms 436 of this aligning bail is secured a longer arm 75.

438 which is pivotally connected with a bail actuating lever 439, as shown in Fig. 14. This bail actuating lever is pivoted at 439^a on the side wall 315 of the oscillatory head 301 and carries a cam 5 roller 440 normally disposed in a depression formed in the periphery of an external cam 441 fixed on the cam shaft 314. This cam is so shaped that, during the first part of the revolution of the shaft 314, the aligning bail will be elevated to disengage its cross-bar 437 from the several transfer pinions 433 so as to permit the pinions to operate; at the completion of the revolution of the cam shaft, the cam roller 440 will drop into the depression in the cam, thus permitting the aligning bail to again engage and align the several transfer pinions.

When the door 400 is opened and the springs 435 swing the transfer pinions 433 out of engagement with the meter, the aligning bail will remain in mesh with the several transfer pinions to maintain them against displacement while thus disengaged. In this instance, the bail will be carried upwardly by the pinions and will cause the cam roller 440 to be slightly elevated from contact with the cam 441; however, this is not detrimental, since these parts are restored to normal positions by the closing of the door.

To prevent accidental displacement of the several meter wheels while the door 400 is open to re-set the wheels, and while the transfer pinions 433 are swung to disengaged position, there is provided a series of retaining fingers 459 which are journaled on a stationary cross-rod 451. As shown in Fig. 16, these retaining fingers are maintained relatively spaced along rod 451 by suitable spacing sleeves 451^a so that they align respectively with the several large transfer gears 424^a, 424^b, 424^c of the meter. As shown in Fig. 13, each retaining finger 459 has a gear engaging nose on its lower end, and its upper end is so disposed as to be engaged by the closed door 400, which thus normally maintains the several retaining fingers out of engagement with the respective transfer gears. Contractile springs 452 connected to the upper ends of the respective retaining fingers 459 and to the hinge rod of the door 400 serve to throw the fingers into engagement with the respective transfer gears when the door 400 is opened.

50 Total or ascending register

This register is of the same construction as the above described metering register insofar as concerns their registering wheels and the associated ratchet and transfer mechanisms, excepting that the indicia of each of its register wheels are inscribed in the opposite direction from that in which the indicia are inscribed on the wheels of the metering register. Consequently while an amount is being subtracted from the total indicated by the descending metering register, the same amount is added by the ascending register to increase the total registered thereon.

The ascending register R^e, as indicated in Fig. 13, includes a series of register wheels 455 journaled on a stationary shaft 456 and associated carry-over discs and transfer gears identical with those similarly associated with the register wheels of the previously described metering register M^e, and a series of transfer pinions 457 journaled on a rod 458 and functioning in the same manner as the transfer pinions 433 of metering register M^e. Similarly to the metering register, the first three register wheels of the ascending register R^e are arranged to be driven by the respective ac-

tuating sectors 500, 500^a, and 500^b through actuating pinions 459 and driving ratchet means 460, which are the same in construction and function as the similar parts in the metering register. However, since this register R^e permanently registers the total of all of the operations of the actuating mechanism and, therefore, is not re-set or otherwise disturbed, it is not provided with any retaining fingers such as the retaining fingers 459 of the metering register; nor does it 10 embody any provisions by which its transfer pinions 457 may be disengaged, the rod 458 upon which these transfer pinions 457 are journaled being mounted directly in the opposite side walls 315, 316, so that said pinions are maintained permanently in mesh with the respective carry-over discs and transfer gears opposite which they are disposed.

The register R^e further differs from the metering register M^e in that it is not provided with a disc such as the disc 434 shown in Fig. 17. In place of such disc the register R^e may be provided with another register wheel so as to extend the capacity of this register to seven places.

As shown in Fig. 13, the register R^e is disposed so that its register wheels may be viewed through a sunken window 461 formed in the top wall 318 of the oscillatory head; to prevent this register from being tampered with, it is surrounded by a sheet metal guard 462 which is supported upon suitable cross-rods carried by the unit side walls 315 and 316 and is slotted as at 462^a to accommodate the respective actuating sectors.

55 Register actuating mechanism

35

This mechanism is designed to oscillate the respective register actuating sectors various distances, depending upon the values to be registered as predetermined by the manual setting of the value selecting means, and includes duplicate 40 devices for differentially actuating the three gear sectors 500, 500^a, and 500^b, which are respectively associated with the fractional cent wheels, the cents wheels, and the dimes wheels of both registers.

The fractional cent sector 500 is loosely journaled on a stationary transverse shaft 501, which is mounted in the opposite side walls 315 and 316 of the oscillatory head 301; as shown in Fig. 13, this sector has an upper abutment edge 502, an arm 503 depending below the shaft 501, and a laterally projecting stop pin 504. Pivotedly mounted at 506 on the lower end of the depending sector arm 503 is a denominational segment 507 which normally is yieldingly maintained against the stop pin 504 by a contractile spring 508 attached to the stop pin 504 and to a similar pin 509 carried by the segment. This segment is adapted to be differentially pre-set to determine the value registering or denominational stroke of the gear sector 500 and, to this end, the segment is provided with a forwardly projecting contact finger 510, and its upper edge, from the base of this finger rearwardly, is toothed to provide a series of nine undercut steps 511 eccentrically arranged so as to be progressively disposed uniformly increasing distances from the pivotal axis 506 of the segment. On the opposite side of the gear sector 500 there is loosely journaled on the stationary shaft 501 a uniform stroke sector actuating bail 512 having a depending arm 513 provided with an anti-friction roller 514. This roller is engaged by the forward forked end of an operating arm 515 which is loosely journaled on the rod 362 and is provided with a 75

cam-roller 516 projecting into the groove of an internal operating cam 517 fixed on the cam shaft 314. The upper end of the actuating bail 512 is bent laterally to extend in front of the abutment edge 502 of the associated gear sector 500, and the forward lateral edge 518 thereof is beveled upwardly and rearwardly so as to properly interlock with the undercut steps of the toothed segment 507.

10 Since the mechanisms which actuate the gear sectors 500^a and 500^b are closely similar to the above described mechanism, which actuates the fractional cent gear sector 500, it is not considered necessary for the purpose of this disclosure to describe each of them in detail. However, to prevent any misconception as to the relative arrangement of these three mechanisms, the similar parts associated with the cents gear sector are designated, particularly in Figs. 12, 16 and 22, by 15 similar reference numerals including an added suffix "a", while those associated with the dimes gear sector are designated by like reference numerals including an added suffix "b". The only difference in these three mechanisms resides in the difference in form of the three operating cams 517, 517^a, and 517^b which are so contoured and timed that the return registering strokes of the fractional cent sector, the cents sector, and the dimes sector are effected in that sequence to allow 20 a transfer to be effected between the fractional cent register wheels and the cents register wheels before the cents register wheels are actuated by the cents sector and to allow a transfer to be effected between the cents register wheels 25 and the dimes register wheels before the dimes register wheels are actuated by the dimes sector.

30 Mounted on the indexing shaft 335 between the printing drum 331 and the stationary stamp 330 there are three value selector discs 520, 520^a, and 520^b, the disc 520 being a fractional cent disc, the disc 520^a a cents disc, and the disc 520^b a dimes disc. These discs are maintained in relatively spaced relationship by spacing washers 521 and are secured to the printing drum 331 by screws 35 45 522. Since the printing drum is fixed on the indexing shaft 335, this method of mounting also secures the discs to the indexing shaft so as to be rotated therewith. The peripheral portions of these discs overlap the respective contact fingers 510, 510^a, and 510^b of the associated denominational segments, as shown in Fig. 12, and are provided with laterally projecting selector studs 523, 523^a, and 523^b, respectively, adapted to engage the contact fingers to selectively pre-set the associated 55 segments.

60 The arrangement of these selector studs of the three value selecting discs will now be explained with particular reference to Figs. 12, 13, 22, and 25. It will be readily understood by those skilled in this art that the particular studs which at any time engage the denominational segments will so pre-set the segments as to effect a registering of a value corresponding to the value of the stamp indicia printing member which is then positioned at the printing position, and that, as the printing drum is rotated to bring different printing members to the printing position, other groups of selector studs will be brought to position to engage the denominational segments. As shown in Fig. 65 70 75 13, these segments are located at a position circularly disposed about ninety degrees back from the printing position; therefore, each group of studs will be located on the respective discs ninety degrees back from the respective correlated print-

ing member on the drum. For instance, in Fig. 13 the printing drum will be considered as being positioned with the printing member for printing a 15 cent stamp disposed at the printing position. At this time the correlated group of selector studs are in engagement with the respective denominational segments, having moved the dimes segment 507^b downwardly and forwardly one step to the one dime position, and the cents segment 507^a five steps to the five cent position, 10 the fractional cent segment 507 remaining in normal position since, in this group, there is no one-half cent stud on the fractional cent selector disc. Since the printing drum of the machine illustrated is provided with eight indicia printing members, there will be eight groups of selector studs on the selector discs, each group being disposed on the discs within forty-five degree limits.

15 This arrangement is illustrated in semi-diagrammatic form in Fig. 25 in which the three selector discs 520, 520^a, and 520^b and the fingers 510, 510^a, and 510^b are shown in the same positions they occupy in Fig. 13. In Fig. 25 the several zero locations on the discs are indicated by broken horizontal lines respectively designated by the reference numerals $\frac{1}{2}^z$, 1^z , $1\frac{1}{2}^z$, 2^z , 4^z , 5^z , 10^z , and 15^z which characterize the lines respectively as the $\frac{1}{2}$ cent zero line, the 1 cent zero line, the $1\frac{1}{2}$ cent zero line, etc. In this embodiment the 15 cent group consists of a dime stud 523^b positioned 20 on the dimes selector disc 520^b one space from the 15 cent zero line 15^z , and a cent stud 523^a positioned on the cents selector disc 520^a five spaces from said 15 cent zero line 15^z , there being no fractional cent stud on the fractional cent disc 25 520 in this group, since the 15 cent value does not require a setting of the fractional cent mechanism. The 10 cent group comprises only a dime stud 523^b positioned on the dimes selector 30 520^b one space from the 10 cent zero line 10^z , no cents stud and no fractional cent stud being required in this group. The 1 cent group, the 2 cent group, the 4 cent group, and the 5 cent group, each comprises a cent stud 523^a positioned on the cents selector 35 520^a, and these are respectively disposed 40 45 one, two, four, and five spaces from the respective zero lines 1^z , 2^z , 4^z , and 5^z , these groups containing no dime studs or fractional cent studs. The $\frac{1}{2}$ cent group comprises only a fractional cent stud 523 positioned on the disc 520 one space from 50 the $\frac{1}{2}$ cent zero line $\frac{1}{2}^z$, no cent stud or dime stud being required in this group, while the $1\frac{1}{2}$ cent group will comprise a similar fractional cent stud positioned on the disc 520 one space from the $1\frac{1}{2}$ cent zero line $1\frac{1}{2}^z$, and a cent stud positioned on 55 the cents selector disc 520^a one space from the zero line $1\frac{1}{2}^z$.

60 Thus, in the $\frac{1}{2}$ cent group, there is a $\frac{1}{2}$ cent stud on the fractional cent disc, in the 1 cent group there is a 1 cent stud on the cents disc, in the $1\frac{1}{2}$ cent group there is a $\frac{1}{2}$ cent stud on the fractional cent disc and a 1 cent stud on the cents disc, in the 2 cent group there is a 2 cent stud on the cents disc, in the 4 cent group there is a 4 cent stud on the cents disc, in the 5 cent group there is a 5 cent stud on the cents disc, in the 10 cent group there is a 1 dime stud on the dimes disc, while in the 15 cent group there is a 5 cent stud on the cents disc and a 1 dime stud on the dimes disc.

65 70 75 However, it is to be understood that this embodiment is merely illustrative of the principle involved since, when a different series of values is desired, other indicia printing members will be substituted, together with other selector discs hav-

ing the studs thereof differently positioned to correspond with the new desired values.

Obviously, the substituted cents and dimes discs could have the studs of the respective groups disposed in any of the nine positions indicated at w in Fig. 25, while the substituted fractional cent disc could have more or less of the $\frac{1}{2}$ cent studs; therefore, the term "group", as applied herein to the studs means those studs, whether one or more, necessary to pre-set the denominational segments to a given value.

The invention therefore contemplates a mechanism adapted to be conditioned to handle any values from $\frac{1}{2}$ cent up to the denominational capacity of $99\frac{1}{2}$ cents for the three bank construction shown and also similar mechanisms in which the denominational capacity has been extended to $999\frac{1}{2}$ cents or higher by adding one or more banks, each including an additional selector disc and associated register actuating mechanism, together with the required additional ratchet drive register wheels.

Registering operation

From the preceding description, it should be evident that the fractional cent register wheels, the cents register wheels, and the dimes register wheels of both the metering register M^e and the total register R^e are respectively operated by substantially duplicate banks of actuating elements, each of which includes a register actuating gear sector meshing with the companion register actuating gear pinions of both registers, and that the ratchet connections between these gear pinions and the associated register wheels are so arranged that the gear pinions will ratchet idly during the forward strokes of the actuating gear sectors and will drive the respective register wheels during the return strokes of the sectors.

Describing the registering operation of the cents bank, with particular reference to Figs. 13 and 22 in which the stepped denominational segment 507^a is shown in a 5 cent denominating position, rotation of the operating cam 517^a will first move the forked operating arm 515^a and its companion sector actuating bail 512^a idly from the normal position shown in Fig. 13 to the position shown in full lines in Fig. 22, at which time the beveled lateral edge 518^a of the bail will engage the fifth step of the pre-set denominational segment 507^a . The cam 517^a will then continue the forward oscillation of the bail 512^a to the end of its uniform stroke and, during this continued oscillation, the bail, together with the segment 507^a and the sector 500^a , will rotate as a unit about the shaft 501 to advance the sector by means of the pivotal connection 506^a between the segment 507^a and the sector 500^a a distance of five teeth to the position indicated in broken lines in Fig. 22. By reason of the ratchet connections associated with the respective register wheels, the wheels will not be rotated during such forward travel of the gear sector; however, upon a return oscillation of the bail, its lateral portion will engage the abutment edge 502^a of the gear segment 507^a and return the segment through the five tooth distance to its normal position and thus cause the associated register wheels to be driven five units or five-tenths of a revolution to register a 5 cent value.

With the parts disposed, as shown in Fig. 13, for the printing and registering of a 15 cent value, the fractional cent denominational segment 507^a is in normal position with all of its steps 511 out of the path of movement of the associated actuating bail 512 , the cents denominational segment 507^a

is in a 5 cent denominating position, and the dimes denominational segment 507^b is in a 1 dime denominating position. With the denominating mechanisms thus pre-selectively set, the metering and registering of the selected value is effected in the following manner during one revolution of the cam shaft 314 .

As the cam shaft 314 rotates, the three forked actuating arms will rock the respective sector actuating bails forward to engage and actuate the pre-set denominational segments and their associated gear sectors in the manner previously explained in connection with Fig. 22. Since the fractional cent denominating segment 507^a in this example, remains in normal position, the associated bail 512 will merely oscillate idly and the fractional cent gear sector will remain stationary in its normal position, while the cents actuating bail 512^a , through engagement with the fifth step 511^a of the cents denominating segment 507^a , oscillates the cents gear sector 500^a forward a distance of five teeth, and the dimes actuating bail 512^b , through engagement with the first step 511^b of the dimes denominating segment 507^b , oscillating the dimes gear sector 500^b forward a distance of one tooth. The oscillated gear sectors will thus be differentially positioned in accordance with the denominational values pre-selectively set up by the differentially movable denominational segments.

By this time, the aligning bail 437 , which normally intermeshes with the several transfer pinions 433 of the metering register M^e (see Figs. 13 and 14) is rocked out of engagement with the pinions by the external cam 441 acting through the cam roller 440 , lever 439 , and the arm 438 which is secured to the bail. These transfer pinions are thus released so that the required transfer operations may be effected during the registering operation of the meter.

As shown in Fig. 13, the operating cam 517 of the fractional cent bank has a drop 517^v immediately following its initial rise, the operating cam 517^a of the cents bank having a similar drop 517^w circularly disposed approximately ninety degrees from the drop of the fractional cent cam 517 , while the dimes operating cam 517^b has a similar drop 517^x circularly disposed approximately ninety degrees from the drop of the cents cam 517^a .

By this arrangement the three sector actuating bails will be returned to normal positions in sequence whereby the gear sectors will successively be rocked rearwardly to rotate the register wheel actuating pinions in a counter-clockwise direction, (as viewed in Fig. 13), whereupon the respective register wheels will be driven through the associated ratchet driving means.

In the operation controlled by the particular pre-selective setting of the denominational segments illustrated in Fig. 13, the fractional cent actuating bail 512 will be restored idly without affecting the fractional cent sector, which has remained in normal position, since no fractional cent value is being registered. The cents actuating bail 512^a will then engage and restore the cents gear sector 500^a and thus drive it rearwardly a distance of five teeth (the same distance that sector was rocked forwardly during the forward oscillation of the bail) to add a 5 cent value on the cents wheel of the total register R^e and to subtract a 5 cent value from the cents wheel of the descending register or meter M^e , subsequently the dimes actuating bail 512^b will restore the dimes gear sector 500^b and

drive it rearwardly a distance of one tooth to add a 10 cent value on the dimes wheel of the total register R^e and to subtract a 10 cent value from the dimes wheel of the descending register 5 or meter M^e .

The particular purpose of thus operating the banks in sequence is to allow a transfer to be effected from a register wheel of lower denomination to the adjacent register wheel of the next 10 higher denomination before the operating mechanism actuates the higher denomination wheel.

Control switches

As shown in Figs. 14 and 16, a shelf 600 extends laterally from the side wall 315 of the oscillatory head 301 of the removable unit MP , and upon this shelf is mounted an electric switch 601 comprising two contact arms, the lower arm 601^a of which is resilient and is extended beyond the upper contact arm. This switch is normally closed and its contact arms are connected by wires 602 with a plug-base 603 secured in an aperture in the outer side wall 305 of the base member 300 of unit MP . As shown in Fig. 1, a plug 604 will be inserted in the plug-base 603 when the unit is disposed in operating position on the machine base. This plug 604 is provided with circuit wires which are preferably enclosed in an electric cable 605 and are included in an electric circuit which connects in series the electric motor 105, a source of electric energy, the switch 601, and a main switch 606 which is mounted in the front wall 104 of the rear housing R^h , as shown in Fig. 1.

35 Meter controlled means for locking the metering printer unit and for disabling the power means

This mechanism is associated with the previously mentioned disc 434 which, as shown in Fig. 17, is secured to the last transfer gear 424^e of the descending meter or register M^e , and provides a means for locking the operating cam shaft 314 of the metering printer unit MP and for, at the same time, opening the switch 601 of the power circuit. In Fig. 14 it is clearly shown that the disc 434 has a notch 434^a formed in its upper edge and that the disc is normally positioned so that the notch is disposed one-tenth of a revolution back from the top of said disc. 45 Adjacent the disc 434 is a depending vertically slidable lock bar 610 having a vertical slot 610^a embracing a guide stud 611 extending inwardly from the unit side wall 315 and a slot 610^b near its upper end which embraces the register shaft 50 409 between the hub of the disc and an adjacent spacing sleeve on the shaft. The upper end of this lock bar 610 is provided with a lateral lug 610^c which normally rests upon the top of the disc 434, as shown in Figs. 14 and 16; the bar is 55 tensioned downwardly by a contractile spring 612 which is attached to an ear formed on the bar and to a stud 613 on the side wall 315. The lower portion of the lock bar 610 is disposed closely adjacent to a lock disc 614 which is fixed 60 on the cam shaft 314 and is provided with a locking recess 614^a formed in its otherwise unbroken circular periphery. Rotatably mounted on the lock bar, directly above the lock disc 614, is a locking roller 615 disposed so as to align with the locking recess 614^a when the lock disc is in normal position. The lock bar extends downwardly 65 in front of the cam shaft 314 and its lower end 610^e is disposed directly above the contact arm 601^a of the electric switch. 70

75 As previously mentioned, the descending meter

is designed to subtract various denominational stamp values from a total amount of prepaid postage initially set up therein until such amount is exhausted and the meter registers zero, and to be further operated to display an "overdraft" 5 figure, the digit of highest denomination of which is a nine.

Obviously, since the transfer or carry-over between any two register wheels of a descending or subtracting register takes place only as the wheel of lower denomination is rotated from the zero indicating position, it follows that an "overdraft" operation involving the rotation of the last meter wheel 406 from zero to nine will through the last transfer pinion 433 and the 15 last transfer gear 424^e, (see Fig. 17) cause the lock control disc 434 to be revolved one-tenth of a revolution to bring its peripheral notch 434^a in alignment with the lateral lug 610^c of the lock bar 610. However, lug 610^c will not, at this time, 20 drop into the aligned notch 434^a because the cam shaft 314 has in its operating cycle rotated the lock disc 614 sufficiently to move its locking recess 614^a from beneath the locking roller 615 which will, under the influence of the spring 612, 25 rest upon the unbroken periphery of the lock disc and be ready to drop into locking recess 614^a when the lock disc completes its operative cycle. Upon completion of such operative cycle, the 30 spring 612 depresses the lock bar 610, the lug 35 610^c entering the notch 434^a of the lock control disc 434, the locking roller 615 entering the locking recess 614^a of the lock disk 614 to lock the cam shaft against further actuation, and the lower end 610^e of the lock bar engaging and 40 depressing the switch arm 601^a to open the switch 601 and thus break the power circuit to the electric motor 105 which drives the machine.

This locking mechanism is thus initially tripped by a transfer or carry-over movement 40 from the meter wheel of highest denomination to the lock control disc 434 upon rotation of the meter wheel from the zero to the nine position in an "overdraft" operation, but does not become effective to lock the cam shaft and meter actuating means operated thereby until the end of such "overdraft" operation; therefore, as such locking mechanism does not restrict the operation of the meter actuating mechanism during the "overdraft" operation, the actuating mechanism 50 may operate the associated meter wheels to indicate any amount of "overdraft" within the denominational capacity of a single metering operation and will thereafter become locked at the end of such "overdraft" operation. Further, 55 it will be evident that, while an "overdraft" operation may be initiated at the time the prepaid postage is exhausted and the meter wheels are at zero, an "overdraft" operation may also be initiated at any time before the prepaid postage 60 is exhausted if the selected denominational value to be registered by such "overdraft" operation is greater than the amount of unused prepaid postage then remaining in the meter.

From the above, it is apparent that neither the meter, the printer, or their actuating mechanisms are locked when the meter wheels are at zero or the amount of prepaid postage is exhausted, or when the meter has been operated 70 a fixed number of times or the printer has made 75 a fixed number of impressions; but, on the contrary, the arrangement disclosed provides an "overdraft" meter controlling a locking mechanism which functions to lock the actuating mechanisms at the end of a final "overdraft"

operation in which the descending meter wheels are turned back past zero to show a complementary figure by which an overdraft may be calculated, with the amount of overdraft depending upon the amount of unused prepaid postage left in the meter just prior to the "overdraft" operation and upon the denomination of the stamp printed during such final "overdraft" operation.

- 10 When the metering printer unit M^p is associated with the machine proper, as shown in Fig. 2, the "Oldham" coupling member 140, which is fixed on the exposed end of the cam shaft 314 of the unit, is engaged with the companion coupling member 139, thus connecting the cam shaft with the main drive shaft 137; for maintaining the unit in proper position on the shelf 50^a of the machine base, unit M^p is provided with two studs 650 which depend from the base member 300 thereof, as shown in Figs. 14 and 16, and project through suitable apertures formed in the shelf in the manner shown in Fig. 13.

15 The lower ends of studs 650 are provided with peripheral grooves 651, and pivoted at 652 on the under side of a depressed web 653 of the shelf 50^a is a forked retaining lever 654 having two arms 655 each provided with a notch 655^a for engaging the groove 651 of one of the studs 650. Both of the notches 655^a face in the same circular direction so as to simultaneously engage or disengage the respective studs, and the lever extends through a slot 654^a in the machine base so that it may be grasped and manually operated.

20 The two studs 650, and another stud 660 depending from the platen retainer 307, extend downwardly to the same level so as to serve as legs for supporting the unit on a substantially level surface when it is removed from the machine, as shown in Fig. 14.

40 Use of the machine

25 Although the machine above described is capable of a wide variety of uses for printing denominational values on relatively flat articles and for registering and metering such values, its greatest utility resides in its use as a multi-denominational "meter mail" machine for printing postage stamps of various denominations upon mail matter; and, while the machine may be so used by the Government post offices, it is also a practice of the manufacturers of these machines to sell the machine outright to a private user and to lease to such user the metering printer head or unit under conditions prescribed by the post office department. These conditions include a provision that the key to the lock 400^c is to remain in the custody of the local post office authorities; it is made a felony for anyone other than these authorities to attempt to open the unit M^p or tamper with the mechanism thereof in any way. The reason for this provision is that the purchase of prepaid postage by a user of the machine involves payment in advance for such prepaid postage and a setting by a post office official of the metering register M^e to indicate the amount of prepaid postage purchased.

30 In connection with "meter mail" machines heretofore proposed, the purchase of prepaid postage has, insofar as we are aware, merely involved payment in advance of the exact amount of postage set up by the post office authorities in the meter.

35 Since the present machine involves an "overdraft" meter permitting operation beyond the point at which the amount of prepaid postage set

up in the meter is exhausted, and since such overdraft may be any amount from the lowest to the highest denominational value within the capacity of a single operation of the machine, the post office conditions for use of this machine will include an 5 additional provision requiring an "overdraft" deposit of an amount equal, at least, to the highest denomination of stamp which the machine is capable of printing. At this time, it may be well to note that the function of the descending meter 10 M^e is to permit any desired amount of prepaid postage, within certain limits, to be set up therein, to meter out this amount of postage as stamps of the same or of different denominations are printed by the metering printer unit M^p , to permit a further "overdraft" actuation after the prepaid postage has been exhausted, and to lock the unit at the completion of such "overdraft" actuation.

15 It is also to be noted that the function of the 20 ascending or total register R^e is merely to keep a record of the aggregate total amount of postage printed by the metering printer unit M^p and to serve as a check against the operation of that unit over a period of time during which the 25 meter M^e has been reset a number of times by the postal authorities.

Purchase of postage

30 It will be understood that, when the metering printer unit M^p is taken to the post office for initial setting, all of the meter wheels are at zero and the cam shaft 314 is locked by the lock bar 610 (see Fig. 14).

35 The user may purchase any desired amount of 35 postage within the capacity of the descending meter M^e , and the post office official will set up this amount in the meter and will actuate the locking mechanism to release the cam shaft and thus condition the actuating mechanism for operation.

40 The manner in which the authorized post office official sets the meter to indicate through the window 400^a the amount of postage purchased is as follows. In order to gain access to the meter 45 M^e , the seal 400^c is broken, the sealing plate 400^e swung aside, the lock 400^e unlocked, and the door 400 swung open away from depressing contact with the arms 431^a of the bell-crank 431. This permits these bell-crank to respond to their 50 springs 435 so as to swing the floating shaft 432, and move the transfer pinions 433 away from meshing engagement with the respective transfer gears and carry-over discs of the meter. The aligning bail 437, moved with the transfer pinions, 55 remains in meshing engagement therewith to maintain them in correct alignment while thus unmeshed with the meter transfer gears.

45 Raising of the door 400 also releases the retaining fingers 450 so that the lower ends thereof 60 are urged by the springs 452 into yielding engagement with the teeth of the respective transfer gears 424^a, 424^c, and 424^e. It is thus rendered easy for the post office official to insert a pick between the teeth of these gears and rotate the 65 meter wheels associated therewith. In this manner the proper indicia of each of the meter wheels is brought into position so that, when viewed through the window 400^a (when the door 400 is closed) the combined indicia of the several wheels 70 thus visible will indicate the amount of postage purchased.

50 In thus re-setting the meter wheels, the lock bar 610 will be elevated to release the cam shaft 314, and the transfer gear 424^e will be rotated 75

backwardly one-tenth of a revolution (two teeth) to restore the lock control disc 434 to the normal position shown in Fig. 14, with its notch 434^a out of alignment with the lug 610^c of the lock bar; 5 the lock bar 610 will then be released so that its lateral lug 610^c again rests upon the unbroken periphery of the lock control disc 434.

When the door 439 is again closed, it will engage the arms 431^a of the bell-cranks 431 to 10 restore the transfer pinions 433 to meshing engagement with their companion transfer gears, and will engage and rock the retaining fingers 450 out of engagement with the transfer gears, as shown in Fig. 13.

15 With the door 400 thus closed, it will be locked by the lock 490^c, the sealing plate 490^e will be closed and sealed, and the purchase of postage will be completed. However, before the user receives the set unit, he is required to deposit at 20 the post office an additional amount sufficient to cover the greatest amount of "overdraft" which the unit is capable of printing, preferably an amount equal to the highest stamp denomination which the unit can print in a single operation.

25 The user returns the unit M^p to his place of business and properly replaces it on the shelf 50^a of the machine base in the manner previously described, the machine now being ready for use.

When the machine is to be used, and if it is 30 desired to print a stamp of a denomination different from that for which the indexing means is set, the operator pulls outwardly on the knob 342^a to withdraw the indexing pin 342 from the engaged indexing hole 339 and rotates the indexing arm 341 clockwise to a new position in 35 accordance with the selected denomination of the stamp to be printed upon the subsequent printing operation, and releases the outward pull on the knob to permit the indexing pin to enter the proper indexing hole to retain 40 the indexing arm in the selected position. This indexing operation pre-selectively positions the printing drum 331 to bring the selected printing member 331^a to the printing position immediately above the impression platen. This indexing of the printing drum also pre-selectively positions the selector discs 520, 520^a, and 520^b to 45 insure subsequent operation of the registering mechanism in accordance with the indexed denomination. With the machine so conditioned, 50 the operator closes the main switch 606 to complete the circuit to the motor 105, whereupon all the parts directly connected with said motor are continuously operated as long as the switch 606 is closed or until the circuit is broken at the 55 switch 601 of the unit M^p by the meter control locking mechanism.

The motor 105 drives the pump P^u which supplies compressed air to the moistening device M and creates a suction or vacuum in the conveyor manifold, and which through the conveyer clutch C^c, drives the conveyer C.

If a stack of envelopes is placed in the hopper H, the conveyer will, in the manner previously 65 described, singly and successively withdraw the envelopes from the bottom of the stack and feed them along the table past the flap-moistening and sealing devices and deliver each sealed envelope to the printing station, where it engages and operates the clutch control trip lever T^c.

70 By operation of the trip lever by an advancing envelope, the conveyer clutch C^c is thrown out to stop the conveyer C, so that the envelope is momentarily arrested at the printing station imme-

dately above the impression platen P^l of the printing mechanism.

With the throwing out of the conveyer clutch C^c, the drive clutch D^c is thrown in to establish a driving connection to the cam shaft of the 5 metering printer unit M^p, whereupon this unit will function, through a single operative cycle, to print the selected stamp indicia upon the envelope, to add on the ascending register R^a the dollars and cents value of the selected stamp 10 indicia printed, and to subtract such value from the total value of prepaid postage indicated by the descending meter M^e, in the manner heretofore explained.

As such single operative cycle is completed, 15 the drive clutch D^c is thrown out and the conveyer clutch C^c is again thrown in to re-establish the drive to the conveyer, which will then eject the printed envelope and bring the succeeding 20 envelope to the printing station.

Normal use of the machine will include the repetition of this cycle many times during each day's run in which the machine will operate in the described manner as long as envelopes are supplied to the hopper, or until it is desired to 25 print a stamp indicia of a different denomination, in which case the main switch 606 will be opened to break the motor circuit and thus stop the machine while the unit M^p is indexed to such different denomination, after which said 30 switch 606 may again be closed, the machine then operating, in the same manner as before, to print stamps of the newly selected denomination.

From the foregoing description, it will be evident 35 that the machine is capable of successively printing stamp indicia of the same or of different denominational values, of subtracting the monetary value of each stamp printed from the total indicated by the descending register or meter, and of adding such values to the total displayed by the ascending register, the amounts of postage printed being at all times reflected in the readings presented by the registers. As successive stamps are printed, the values thereof 40 are successively deducted from the value remaining in the descending register or meter after the previous operations until, eventually, the entire 45 value of prepaid postage has been used and the several wheels of the descending register or meter all register zero.

At such time, the machine is fully capable of functioning through an additional operative cycle to effect, what is herein termed, an "overdraft" operation, in which the descending meter 55 wheels are turned back past zero to show a complementary figure by which an overdraft may be calculated by the postal authorities. For example, with the meter wheels restored to zero and the mechanism indexed to print and register 60 a stamp of 1½ cent denomination, the "overdraft" operation will cause the first actuating sector to rotate the fractional cent meter wheel one space from 0 to ½ and thus effect a transfer or carry-over, causing all of the other meter 65 wheels to rotate one space, the meter now reading 999.99½ and the lock control disc 434 thereof being rotated by the carry-over from the last meter wheel to the disc one-tenth of a revolution to bring its notch 434^a into alignment with 70 the lateral lug 610^c of the lock bar 610. As previously explained, this does not render the lock bar effective to lock the cam shaft 314, but merely conditions this lock mechanism so that it may function at the completion of the "over- 75

draft" cycle. Continuing the "overdraft" operation, the cents meter wheel will be rotated one space by its actuating sector, the meter wheels now reading 999.98½, which is a complementary figure by which the amount of overdraft can be calculated by the postal authorities. This completes this "overdraft" operation, the last step of which will bring the recess 614a of the lock disc 614 into registry with the locking roller 615 carried by the lock bar 619, whereupon this lock bar is immediately pulled downwardly by the spring 612 to engage its locking roller in the recess of the disc 614 and thereby effectively lock the cam shaft 314, the lower end 610e of said lock bar at the same time opens the switch 601 to break the motor circuit.

In this manner, the machine is stopped and the metering printer unit M^p is locked at the end of such an "overdraft" operation.

An "overdraft" operation may also take place before the postage is exhausted and before the meter wheels are restored to zero in instances in which the amount of unused postage remaining in the meter is less than the denomination of stamp to be printed by the "overdraft" operation. For example, with the meter wheels showing \$000.020 of unused postage, the printing of a 5 cent stamp will cause the meter wheels to successively show 000.010—000.000—999.990—999.980—999.970, the last of which is the complementary "overdraft" figure. In this example, the transfer movement from the last meter wheel to the lock control disc 434 takes place when the meter wheels move from 000.000 to 999.990 to condition the locking mechanism for subsequent operation at the end of the "overdraft" operation to lock the cam shaft and open the switch 601 in the manner before explained.

After a final "overdraft" operation and before the unit can again be used, it must be taken to the post office at the time of purchase of additional postage, so that an authorized post office official may calculate the amount of overdraft, reset the meter wheels to indicate the amount of purchased postage, and release the cam shaft by normalizing the locking mechanism.

In calculating the amount of overdraft, the complementary figure showing on the meter wheels of meter M^p will be subtracted from the next whole number greater than the maximum capacity of the meter, which number will be 1,000.000 for the meter herein disclosed.

For instance, in the first example above explained, the complementary figure 999.98½ will be subtracted from 1,000.000 to leave 000.01½, which designates an overdraft of 1½ cents. In the second example above explained, the complementary figure 999.970 will be subtracted from 1,000.000 to leave 000.030, which designates an overdraft of 3 cents. Thus, in the first example, the overdraft is equal to the denomination of the 1½ cent stamp last printed, while in the second example 2 cents of the value of the 5 cent stamp last printed was paid for by the unused balance of postage then remaining in the meter, leaving 3 cents of the value to be carried over into the "overdraft" figure.

It will thus be apparent that such overdrafts will vary from time to time and will depend entirely upon the amount of unused postage remaining in the meter just prior to the overdraft operation and upon the denomination of the stamp printed during this final "overdraft" operation.

With the overdraft thus calculated, the user pays a desired amount for the purchase of additional postage; after deducting from the amount of such payment the amount of the calculated overdraft, the post office official will, in the manner heretofore explained, set the meter wheels to indicate the residual amount, which then defines the amount of prepaid postage which may be printed by the pre-set unit before a subsequent resetting becomes necessary. The post office official will then normalize the locking mechanism to release the cam shaft of the unit and close the switch 601 thereof, and will close, lock, and seal the door of the unit, after which the unit is returned to the user, the "overdraft" deposit remaining with the postal authorities to cover a subsequent overdraft.

It is believed that the foregoing description will be sufficient to enable those skilled in this art to fully understand the constructions, functions, and purposes of the several associated mechanisms; and, while the particular embodiment herein illustrated and described is admirably adapted to fulfil the objects primarily stated, it is to be understood that it is not intended to confine the invention to the one form of embodiment herein disclosed, for it is susceptible of embodiment in various forms, all coming within the scope of the claims which follow.

What we claim is:

1. In a device of the character described rotatably adjustable denominational selector discs, selector elements thereon respectively representing different denominational values, an oscillatable stepped member associated with each of said discs, each stepped member being engageable by a selector element on its associated disc to position said stepped member differentially to represent the denominational value of the positioned selector element, means urging said stepped members against said selector elements; a register, an oscillatable register-operating gear sector associated with each stepped member and movable relative to said stepped member, and an oscillatable member positioned between said gear sector and its associated stepped member, said oscillatable member being operable to engage and drive its associated stepped member while the latter is selectively positioned by its respective selector element for defining the extent of movement of said register-operating sector to correspond with the denominational value represented by said positioned stepped member and by said denominational disc.

2. In a device of the character described, a rotatably adjustable drum, selector discs attached to and adjustable with said drum, said discs having selector studs thereon respectively representing different denominational values, a differentially actuated stepped member register means, oscillatable means comprising a sector engaging said register means and an element engageable with said differentially actuated stepped member, means for moving said oscillatable means, said stepped member being in the path of said element, said stepped member being engageable by one of said selector studs and selectively positioned thereby to determine the extent of movement of said oscillatable means, whereby said register means is actuated in accordance with the setting of said selector discs.

3. A machine of the character described, comprising register means, differentially settable rotatable means having denominational selector

elements thereon, an oscillatable differentially actuated stepped member movable relative to said differentially settable means, said stepped member being differentially engageable by said selector elements and positioned thereby in accordance with the setting of said differentially settable means, and register actuating means including an element operable to engage said stepped member and to move therewith, the differential actuation of said register by said register actuating means being defined by the differential positioning of said stepped member as preset by engagement of said member by its associated positioned selector element.

4. In a machine of the character described, register means including a register gear wheel, differentially settable rotatable denominational means having selector elements thereon, an oscillatable differentially actuated stepped member movable relative to and engageable by a selector element to position said stepped member in accordance with the adjustment of said denominational means, and register-actuating means including a gear sector engaging said gear wheel and a member engageable with said stepped member while positioned by said selector element, the extent of movement of said gear wheel by said gear sector varying in accordance with the selective positioning of said selector elements and said stepped member.

5. In a machine of the character described, register means including a gear, oscillatable register-actuating gear means engaging said register gear, a differentially actuated stepped oscillatable member, a movable member adapted to engage said stepped member and said oscillatable gear means and differentially settable selector means adapted to engage said stepped member and define the movement of said oscillatable gear means to correspond to the denominational value represented by the positioned selector element, said movable member being operable to effect relative movement between said register-actuating means and said selector elements while said selector elements are selectively positioned to set up a corresponding amount on said register.

6. In a device of the character described, adjustable denominational selector means having selector elements thereon, register means, register operating means comprising an oscillatable gear member, a differentially actuated oscillatable stepped member movable relative to said selector means and said register-operating means, said selector elements engaging and positioning said stepped member in accordance with the particular denominational value represented by the selector element positioned, and movable actuator means in one direction of movement engaging said stepped member while the latter is positioned by its selector element, in the opposite direction of movement, engaging and moving said gear member, whereby the extent of movement of said register-operating means is defined in accordance with the adjustment of said selector means.

7. In a device of the character described, rotatably adjustable denominational selector discs, selector elements thereon respectively representing different denominational values, an oscillatable stepped member associated with each of said discs, each stepped member being engageable by a selector element on its associated disc and being thereby positioned differentially by the adjustment of said disc to represent the denominational value of the positioned selector element, means urging said stepped members against said selector elements, a register, an oscillatable register-operating gear sector associated with each stepped member and movable relative to said stepped members, an oscillatable actuator adapted to engage said stepped member while the latter is selectively positioned by its respective selector element, operation of said actuator in one direction moving said stepped member relative to said selector element, and said actuator, upon movement in the opposite direction, engaging and moving said gear sector the extent of movement of said register-operating sector corresponding with the denominational value represented by said positioned stepped member and positioned denominational disc.
